RAILWAY SIGNALING SYSTEM

Ralph R. Kemmerer, Swissvale, Pa., assignor to
The Union Switch & Signal Company, Swiss-
vale, Pa., a corporation of Pennsylvania

Application June 30, 1939, Serial No. 282,185

32 Claims. (Cl. 246—34)

My invention relates to railway traffic controlling apparatus and it has special reference to the organization of such apparatus into signaling systems of the class wherein coded track-way energy is utilized to control either or both the wayside signals or train carried cab signals.

The system provided by this invention is an improvement on that shown and claimed in the application of Howard A. Thompson, Serial No. 210,743, filed May 28, 1938, for Railway traffic controlling apparatus.

In the above mentioned application there is shown a signal system incorporating at each signal location a "lockout" circuit which is arranged to effect the supply of steady uncoded energy to the circuit of the adjacent track section in the rear of a signal location in the event that the insulated joint separating the track sections in the rear and in advance of the signal location are defective so that energy supplied to the rear track section feeds over the defective insulated joint and energizes the track relay of the forward section.

As a result of operation of the "lockout" circuit shown therein, the track relay at the signal location having the defective insulated joint is maintained constantly energized and the signal at that location displays its most restrictive aspect.

Similarly, the track relay for the rear section being supplied with steady uncoded energy, conditions the signal which it controls to display its most restrictive aspect, while steady energy is supplied to the track section in the rear of that signal, and so on until an interlocking or other interruption in the signal system, such as special cut section facilities, is reached.

The mode of operation of the signal system shown in the Thompson application in the event of a defective insulated joint creates a safe condition as it insures that the signal at the location of the defective joint will display its most restrictive indication, but as the signals throughout the track stretch for a considerable distance in the rear of the defective joint are also conditioned to display their most restrictive aspects, movement of traffic in the track stretch is considerably delayed.

As pointed out above, the "lockout" circuit shown in the above identified application is arranged so that on the supply of steady uncoded energy to a track relay steady uncoded current will be supplied by the "lockout" circuit associated with that track relay to the track circuit of the adjacent section in the rear. This prevents the use of steady energy in a track circuit to dis-

continue operation of a highway crossing signal, or for other purposes, since if steady energy is supplied to a track circuit for this purpose all of the signals in the rear will be caused to display their most restrictive indications even though the track stretch is unoccupied. 5

It is an object of this invention to provide an improved "lockout" circuit which will operate in the event an insulated joint is defective to cause the signal at that location to display its 10 most restrictive indication and to supply steady non-coded energy to the track circuit of the adjacent track section in the rear, but which when the track relay is supplied with steady uncoded energy by means in advance of the track relay will not operate to supply uncoded energy to the track circuit of the adjacent track section in the rear. 15

A further object of the invention is to provide 20 an improved "lockout" circuit which is non-cascading in operation.

Another object of the invention is to provide an improved "lockout" circuit which is arranged to supply coded energy to the track circuit of the adjacent track section in the rear for a predetermined period after operation of the track relay is initiated, after which a circuit is established to supply steady uncoded energy to the track section in the rear, the supply of steady energy being interrupted and the supply of coded energy resumed if and only if the track relay continues to follow code, whereby the supply of steady energy to the track section in the rear will be continued if an insulated joint separating two sections is defective so that steady energy supplied to the rear section feeds over the defective joint and maintains the track relay of the forward section constantly energized to thereby prevent the operation of the track relay necessary to interrupt the steady energy supply circuit. 30 35 40

A further object of the invention is to provide an improved "lockout" circuit for use in a coded signaling system, the "lockout" circuit being arranged so that it is not established on the first operation of the contacts of the code following track relay, whereby steady energy may be supplied to a track section to effect picking up of the contacts of the track relay of that section without establishing the "lockout" circuit with the resultant supply of steady uncoded energy to the track section in the rear. 45 50

Another object of the invention is to provide an improved "lockout" circuit which will make it unnecessary to employ the special cut section 55

facilities heretofore required to prevent the cascading action present when other types of "lock-out" circuits are employed.

Other objects of my invention and features of novelty will be apparent from the following description taken in connection with the accompanying drawings.

I shall describe one form of apparatus embodying my invention, and shall then point out the novel features thereof in claims.

In the drawings, Fig. 1 is a diagram of a stretch of railway track equipped with traffic controlling apparatus embodying my invention, and

Fig. 2 is a diagram of a stretch of railway track including an intersection with a highway together with equipment embodying my invention for controlling operation of signals for protecting the highway crossing.

20 Construction of the equipment shown in Fig. 1 of the drawings

Referring to Fig. 1 of the drawings, there is shown therein a pair of track rails 1 and 2 forming a stretch of railway track over which traffic normally moves in the direction indicated by the arrow, that is, from left to right. The rails of the track stretch are separated by insulated joints 3 into the customary successive track sections and the rails of each of these sections form a part of a track circuit of the usual character.

The particular track stretch which is represented in Fig. 1 is intended for use in a railway system employing electric current for propulsion purposes, and for this reason alternating current track circuit energy is used together with impedance bonds 4 of the customary form which conduct propulsion current around each pair of insulated rail joints. As the description proceeds, however, it will be apparent that the apparatus of my invention is equally well suited for use on a steam road in which the application of either direct current or alternating current track circuit energy for control of the signals may be used. In such an application the impedance bonds 4 would of course be omitted.

In the diagram forming Fig. 1 two complete track sections are shown, these being identified as sections 11T and 12T. Each of these track sections has located at the entrance end thereof a signal for governing movement of trains in the track stretch, the signal for section 11T being identified as 11S, and the signal for section 12T being designated 12S. The signals illustrated are of the familiar color light type having a green or clear lamp G, a yellow or caution lamp Y, and a red or stop lamp R.

While this invention is illustrated and described in connection with a signal system employing wayside signals, it should be understood that the invention is applicable also to a signal system having cab signals only.

The rails of each of the track sections form a part of a track circuit to which coded alternating current train control energy is supplied at the exit or leaving end from the secondary of a track transformer TT with a prefix corresponding to that of the associated track section. The circuits for supplying current from the track transformers TT include the usual current limiting reactors RA. The energy supplied to the track circuits is derived from any suitable source and may be distributed throughout the track stretch by a transmission line, not shown. In the drawings the reference characters BX and CX designate 75 the terminals of such power supply source and it

will be assumed that the energy supplied from this source is alternating current with a frequency of 100 cycles per second.

Each of the signal locations has associated therewith a suitable source of direct current, such as a primary or a storage battery, not shown, the terminals of which are designated in the drawings B and C.

The particular signaling system shown in Fig. 1 is of the three-indication variety and it makes use of track circuit energy of two different codings. This coded energy is provided by code transmitters CT which interrupt the supply circuit of the associated track transformer a definite number of times per minute according to traffic or other conditions ahead. In the illustrative form shown each code transmitter CT is provided with two circuit making and breaking contacts 80 and 180 which are continuously actuated by a motor or other suitable mechanism at two different speeds. For purposes of illustration it will be assumed that these speeds are such as to provide 80 and 180 energy impulses per minute which are separated by periods of equal duration in which no energy is supplied.

Each of the track sections includes a track relay designated TR together with an appropriate prefix, while the track relay is located at the entrance end of the track section with which it is associated. The track relays may be of any suitable type, and as shown are of the direct current type having their windings connected to the track rails of the associated track sections through suitable resonant units RU shown diagrammatically in the drawings.

The resonant units RU each comprise a transformer, a capacitor and a reactor so arranged and proportioned as to freely pass the 100 cycle coded signal control energy, but so as not to pass propulsion current of a different frequency, while a rectifier is incorporated in each unit to convert into direct current the alternating current which is supplied through the unit.

The track relays TR are provided with contacts 15 and 16 which when the relay winding is de-energized occupy their lower or released positions, as indicated by dotted lines, while when the relay winding is energized, the contacts 15 and 16 occupy their upper or picked up positions, as shown.

Each of the track relays has associated therewith two front contact repeater relays FSA and FSB, two back contact repeater relays BSA and BSB, and two signal control relays J and H.

The apparatus associated with the signals 11S and 12S are duplicates of each other and accordingly only the apparatus at signal 12S will be described in detail. Referring to the equipment at signal 12S, the contacts 15 and 16 of the relay 12TR are connected by wire 17 to terminal B of the local source of direct current. Contact 16 when released engages a back contact 18 which is connected by wire 20 to contact 21 of relay 12FSB and to one terminal of snubbing resistor 23 associated with relay 12BSB. Contact 21 of relay 12FSB when picked up engages a contact 24 which is connected by wire 25 to one terminal of the winding of relay 12BSB, the other terminal of which is connected to a terminal of snubbing resistor 23 and to terminal C of the local source of direct current. Contact 21 of relay 12FSB when released engages a contact 27 which is connected by wire 28 to contact 29 of relay 12FSA, while relay 12FSA has a contact 30 which when picked up engages contact 29. 75

Contact 30 is connected by wire 32 to one terminal of a snubbing resistor 34 and also to one terminal of the winding of relay 12BSA. The other terminals of the resistor 34 and of the winding 5 of relay 12BSA are connected to terminal C of the source of current.

When contact 16 of relay 12TR is picked up, it engages a contact 36 which is connected by wire 38 to contacts 39 and 42 of relay 12FSB, to one terminal of snubbing resistor 40 associated with relay 12FSB, to contact 41 of relay 12BSA, and to contact 43 of relay 12H.

Contact 39 of relay 12FSB when released engages a contact 45 which is connected by wire 46 to one terminal of the winding of relay 12FSA, 15 and also to one terminal of snubbing resistor 47 associated with the relay 12FSA. The other terminals of the relay winding and of the resistor 47 are connected to terminal C of the source of current.

Contact 39 of the relay 12FSB when picked up engages a contact 49 which is connected by wire 50 to contact 51, while relay 12BSB has a contact 52 which when picked up engages contact 25 51. Contact 52 is connected by wire 54 to one terminal of the winding of relay 12FSB, the other terminal of which is connected to a terminal of snubbing resistor 40 to terminal C of the source of current.

Relay 12BSA has a contact 55 which when 30 picked up engages contact 41. Contact 55 is connected by wire 57 to contact 58 of relay 12H, while a branch of wire 57 is connected to contact 59 of relay 12FSB. Contact 59 when picked up 35 engages a contact 42, while relay 12H has a contact 60 to which is connected a branch of wire 54 and which when released engages contact 58.

Relay 12H has a contact 62 which when released engages contact 43 and which is connected by wire 64 to contact 65. Relay 12BSB 40 has a movable contact 66 which when picked up engages contact 65 and which is connected by wire 67 to a terminal of the winding of relay 12H, the other terminal of which is connected to terminal C of the source of current. A snubbing resistor 70 is connected across the terminals of the winding of relay 12H.

Contact 62 of relay 12H when picked up engages contact 71 which is connected by wire 72 to terminal B of the local source of current.

The relays 12FSB, 12BSB, and 12H have contacts which control the circuit of the primary winding of track transformer 11TT. One terminal of the primary winding 74 of the track 50 transformer is connected to terminal CX of the source of 100 cycle alternating current, while the other terminal of the winding 74 is connected by wire 75 to contact 76 of relay 12FSB and to the 55 80 code contact of coding relay 12CT.

Contact 76 when picked up engages a contact 60 77 which is connected by wire 78 to contact 79 of relay 12BSB, and to contact 82 which is engaged at times by contact 80 of relay 11CT.

Contact 79 of relay 12BSB when released engages contact 84 which is connected by wire 85 to terminal BX of the source of alternating current, while contact 79 when picked up engages contact 87 which is connected by wire 89 to contact 90 of relay 12H. Contact 90 when picked up engages contact 92 which is connected by wire 70 93 to contact 94, which is intermittently engaged by contact 180 of coding relay 12CT.

The relays 12J and 12H have contacts which control the circuits of the lamps of signal 12S. The relay 12H has a contact 95 which is connected by wire 96 to terminal B of the local source 75

of current. Contact 95 when released engages contact 97 which is connected by wire 98 to one terminal of the lamp R, the other terminal of which is connected by wire 100 to terminal C of the local source of current. As long as contact 95 of relay 12H is released, a circuit is established to illuminate the red or stop lamp R of signal 12S.

When contact 95 of relay 12S is picked up, the circuit of lamp R is interrupted, while contact 95 engages contact 101 which is connected by wire 102 to contact 103 of relay 12J. Contact 103 when released engages contact 104 which is connected by wire 105 to one terminal of the yellow lamp Y, the other terminal of which has a branch of wire 106 connected thereto. Accordingly, when contact 95 of relay 12H is picked up and contact 103 of relay 12J is released, a circuit is established to illuminate the yellow or caution lamp Y of signal 12S.

When contact 103 of relay 12J is picked up, it 20 interrupts the circuit of the lamp Y, while it engages a contact 107 which is connected by wire 108 to one terminal of lamp G, the other terminal of which has connected thereto a branch of wire 109. Accordingly, when contacts 95 and 103 are both picked up, a circuit is established to illuminate the green or clear lamp G of signal 12S.

As pointed out above, the equipment associated with signal 11S is a duplicate of that associated 30 with signal 12S so it is unnecessary to repeat a description of the construction of this apparatus.

The equipment is shown in Fig. 1 of the drawings in the condition which is assumed when the sections 11T and 12T are both unoccupied, and 35 when there is at least one unoccupied section in advance of section 12T with the result that coded current of the 180 code frequency is supplied by transformer 12TT to the track circuit of track section 12T.

As section 12T is supplied with current of 180 40 code frequency, the contacts of the track relay 12TR will be picked up and released periodically in accordance with this code frequency.

During the picked up periods of the relay contacts, contact 16 establishes a circuit to energize the winding of relay 12FSB, this circuit being traced from terminal B of the source of current through wire 17, contacts 16-36 of relay 12TR, wire 38, contacts 39-49 of relay 12FSB, wire 50, 50 contacts 51-52 of relay 12BSB, wire 54, and winding of relay 12FSB to terminal C of the source of current. As the winding of relay 12FSB is energized, the relay contacts are picked up.

In addition, at this time the snubbing resistor 55 40, which is connected between wire 39 and terminal C of the source of current, is shunted across the terminals of the winding of relay 12FSB with the result that the relay contacts are rendered slow in releasing. The contacts of relay 12FSB, therefore, remain picked up during the released periods of the contacts of the code following track relay 12TR, during which time no energy is supplied to the winding of relay 12FSB.

During the released periods of the contacts of 65 track relay 12TR, a circuit is established to energize the winding of relay 12BSB. This circuit is traced from terminal B of the source of current through wire 17, contacts 16-18 of relay 12TR, wire 20, contacts 21-24 of relay 12FSB, wire 70 25, and winding of relay 12BSB to terminal C of the source of current. As the winding of relay 12BSB is energized, the contacts of the relay are picked up. At this time the snubbing resistor 75 23 is shunted across the winding of relay 12BSB.

with the result that the relay contacts are slow in releasing and remain picked up during the picked up periods of the track relay contacts.

At this time the winding of relay 12H is energized by current supplied over a circuit which is traced from terminal B of the source of current through contacts 71-62 of relay 12H, wire 64, contacts 65-66 of relay 12BSB, wire 67, and winding of relay 12H and snubbing resistor 70 in parallel therewith to terminal C of the source of current. As the winding of relay 12H is energized, the contacts of the relay are picked up, and as the snubbing resistor 70 is shunted across the relay winding, the contacts of the relay are slow in releasing.

As the track relay 12TR is following code of the 180 code frequency, its contact 15 alternately engages contacts 110 and 112 which are connected by wires 114 and 115 to the resonant unit RUA. 20 On operation of the track relay contact at this frequency the resonant unit 12RUA is effective to energize the winding of relay 12J with the result that the contact 103 of relay 12J is picked up.

25 As contact 95 of relay 12H and contact 103 of relay 12J are picked up, the circuit to energize the green lamp G of signal 12S is complete, and this lamp is illuminated to indicate that there are at least two unoccupied blocks in advance 30 of the signal.

As the contacts of relays 12H, 12BSB, and 12FSB are picked up, a circuit is established to supply the primary winding 74 of track transformer 11TT with energy periodically interrupted by the 180 coding contact of code transmitter 12TT. This circuit is traced from terminal BX of the source of alternating current through contacts 180-94 of code transmitter CT, wire 93, contacts 92-90 of relay 12H, wire 40 89, contacts 87-79 of relay 12BSB, wire 78, contacts 77-76 of relay 12FSB, wire 75, and primary winding 74 of track transformer 11TT to terminal CX of the source of alternating current.

Accordingly current of the 180 code frequency is supplied by the secondary winding of track transformer 11TT to the track circuit of track section 11T, while the equipment associated with signal 11S is conditioned to illuminate the green lamp of signal 11S and to supply energy of the 180 code frequency to the adjacent track section in the rear, that is, to the track section 10T.

At this time as contact 39 of relay 12FSB is picked up, it interrupts the circuit of the winding of relay 12FSA, while as contact 21 of relay 55 12FSB is picked up, it interrupts the circuit of the winding of relay 12BSA.

The circuit of the winding of relay 12BSA is additionally interrupted by contact 30 of relay 12FSA which is released at this time. It will be 60 seen, therefore, that at this time the relays 12FSA and 12BSA are deenergized and their contacts are released.

In similar manner the relays 11FSA and 11BSA are deenergized and their contacts are released.

65 *Operation of equipment shown in Fig. 1 on passage of a train*

If while the equipment is in the condition shown, a train moving from left to right enters 70 the track section 11T, the equipment on the locomotive will receive current of the 180 code frequency and the cab signal apparatus carried thereby will respond to current of this frequency to give a clear indication.

75 When the locomotive enters the track section

11T, it shunts the track relay 11TR with the result that this relay no longer responds to the coded energy supplied to the track rails of the track section by the transformer 11TT, and the contacts of the relay 11TR remain in their released 5 positions.

As the contact 16 of relay 11TR does not engage its front contact, the circuit for energizing the winding of relay 11FSB is not established and the contacts of relay 11FSB become released 10 after the expiration of a time-interval determined by the release time of the relay.

On shunting of the track relay 11TR the contact 16 thereof becomes released if it is not already in that position thereby completing the 15 circuit for energizing the relay 11BSB. However, as soon as the contacts of relay 11FSB become released, contact 21 of relay 11FSB interrupts the circuit for energizing the winding of relay 11BSB, while this contact when released also 20 opens the circuit by which snubbing resistor 23 is shunted across the winding of relay 11BSB. Accordingly on release of contact 21 of relay 11FSB relay 11BSB is deenergized, and the contacts thereof quickly become released. 25

On release of the contacts of relay 11BSB contact 66 interrupts the circuit of the winding of relay 11H, and after a brief time interval the contacts of relay 11H become released. On the release of contact 95 of relay 11H the circuit for 30 energizing the green lamp G of signal 11S is interrupted, and the circuit for energizing the red lamp R of the signal is complete so the signal now displays its stop indication.

When the track relay 11TR is shunted and no longer follows code, its contact 15 remains in engagement with its back contact 112 and does not intermittently engage contact 110 with the result that resonant unit 11RUA is no longer effective to supply energy to the winding of relay 11J. 40 Accordingly relay 11J becomes deenergized and its contact 103 becomes released. Because of the inherent characteristics of the resonant unit 11RUA, relay 11J does not release instantaneously on cessation of operation of contact 15 of relay 45 11TR and contact 103 remains picked up for a brief time interval. As a result, contact 103 may remain picked up until after contact 95 of relay 11H becomes released to interrupt the circuit for energizing the green lamp G. 50

If, however, contact 103 becomes released before contact 95 becomes released, the circuit for energizing the green lamp G will be interrupted, while contact 103 will establish the circuit to energize the yellow lamp Y. On subsequent release 55 of contact 95 of relay 11H the yellow lamp will become extinguished and a circuit to illuminate the red lamp will be established. This brief flash of the yellow lamp is not objectionable since it does not occur until after the locomotive has 60 passed the signal 11S.

On release of contact 76 of relay 11FSB the circuit for supplying energy of 180 code frequency to the primary winding 74 of track transformer 10TT is interrupted, while on release of contact 65 79 of relay 11BSB a circuit is established to supply current of 80 code frequency to the primary winding 74 of track transformer 10TT.

This circuit is traced from terminal BX of the source of alternating current through wire 85, 70 contacts 84-79 of relay 11BSB, wire 78, contacts 82-80 of code transmitter 11CT, wire 75, primary winding 74 of track transformer 10TT, and terminal CX of the source of current.

As the train continues through the track 75

stretch and enters track section 12T, it shunts the track relay 12TR, and the equipment associated with this track relay operates in the manner described in detail in connection with section 5 11T to cause the signal 12S to display its red or stop indication, while the supply of current of 180 code frequency to section 11T is cut off, and current of the 80 code frequency is supplied to the primary winding 74 of track transformer 10 11TT.

As long as any portion of the train remains in track section 11T, the track relay 11TR is shunted and does not follow the current of 80 code frequency supplied by the track transformer 15 11TT.

When the train advances far enough in the track stretch that the rear of the train passes out of the track section 11T, the track relay 11TR is no longer shunted and its contacts become 20 picked up and released in response to current of the 80 code frequency supplied by track transformer 11TT.

On the first picked up period of the contacts of the track relay 11TR which may be considered 25 the first operation of the relay contacts, contact 16 establishes a circuit to energize the winding of relay 11FSA. This circuit is traced from terminal B of the source of current through wire 17, contacts 16-36 of relay 11TR, wire 38, contacts 30 39-45 of relay 11FSA, wire 46, and winding of relay 11FSA and snubbing resistor 47 in parallel to terminal C of the source of current.

As a result of energization of the winding of relay 11FSA, the contact 30 of this relay becomes 35 picked up and establishes the circuit for energizing the winding of relay 11BSA, and on the first released period of the contacts of relay 11TR the circuit for energizing the winding of relay 11BSA is complete.

40 On the first released period of the contacts of the track relay 11TR following the first picked up period, which may be considered the second operation of the relay contacts, contact 16 engages contact 18 and establishes the circuit for 45 energizing the winding of relay 11BSA. This circuit is traced from terminal B of the source of current through wire 17, contacts 16-18 of relay 11TR, wire 20, contacts 21-27 of relay 11FSB, wire 28, contacts 29-30 of relay 11FSA, wire 32, 50 and winding of relay 11BSA and snubbing resistor 34 in parallel to terminal C of the source of current.

As a result of energization of the winding of relay 11BSA, contact 55 of this relay becomes picked 55 up and establishes a pick-up circuit for the winding of relay 11FSB so that relay 11FSB is energized on the next picked up period of the contacts of the relay 11TR, which may be considered as the third operation of the relay contacts.

60 The circuit for energizing the winding of relay 11FSB is traced from terminal B of the source of current through wire 17, contacts 16-36 of relay 11TR, wire 38, contacts 41-55 of relay 11BSA, wire 57, contacts 58-60 of relay 11H, wire 54 to 65 the winding of relay 11FSB, the other terminal of which is connected to terminal C of the source of current.

It will be seen that connection is established 70 from wire 38 to one terminal of the winding of relay 11FSB, while wire 38 is directly connected to one terminal of snubbing resistor 40, and that the other terminal of the snubbing resistor 40 is connected to the other terminal of the winding of relay 11FSB. As a result, the snubbing resistor 40 75 is shunted across the winding of the relay and

renders the relay contacts slow in releasing with the result that these contacts will be maintained picked up during brief periods in which the energizing circuit of the relay winding is interrupted by the track relay contacts.

As a result of energization of the winding of relay 11FSB, the contacts of this relay become picked up and interrupt the previously traced circuit for energizing the windings of relays 11FSA and 11BSA, while on picking up of contact 10 16 of relay 11FSB the "lockout" circuit for this track section is established and steady energy is supplied to the primary winding 74 of the track transformer 10T of the adjacent section in the rear. The "lockout" circuit for supplying steady 15 energy is traced from terminal BX of the source of alternating current thorough wire 85, contacts 84-79 of relay 11BSB, wire 78, contacts 77-76 of relay 11FSB, and wire 75 to one terminal of the primary winding 74 of track transformer 20 10TT, the other terminal of which is connected to terminal CX of the source of current.

If the contacts of the track relay 11TR continue to follow code then on the next or fourth operation of the relay contacts, which is their 25 second released period, a circuit is established to energize the winding of relay 11BSB. This circuit is traced from terminal B of the source of current through wire 17, contacts 16-18 of relay 11TR, wire 20, contacts 21-24 of relay 30 11FSB, wire 25, and winding of relay 11BSB to terminal C of the source of current. In addition, it will be seen that wire 20 is connected to one terminal of the snubbing resistor 23, the other terminal of which is connected to a terminal of 35 the winding of relay 11BSB with the result that the snubbing resistor 23 is shunted across the relay winding to render the relay contacts slow in releasing.

On picking up of the contacts of relay 11FSB 40 contact 59 engages contact 42 to establish a circuit through which current may be supplied to the winding of relay 11FSB during the picked up periods of the track relay contacts. This prevents deenergization of the winding of relay 45 11FSB on opening of contact 55 of relay 11BSA.

In addition, on picking up of the contacts of relay 11FSB contact 39 of the relay engages contact 49 to establish a stick circuit for the winding of relay 11FSB, this circuit being completed on 50 picking up of contact 52 of relay 11BSB. The stick circuit for the winding of relay 11FSB is traced from wire 38 through contacts 39-49 of relay 11FSB, wire 50, contacts 51-52 of relay 11BSB, wire 54, winding of relay 11FSB, and terminal C of the source of current. It will be seen 55 also that at this time snubbing resistor 40 is shunted across the winding of relay 11FSB so that the contacts of the relay are slow in releasing and will bridge over the released periods 60 of the contacts of track relay 11TR.

In addition, on picking up of the contacts of relay 11BSB contact 66 establishes a circuit for energizing the winding of relay 11H, this circuit being complete on the third picked up period of 65 the track relay contacts, that is, the fifth operation of the relay contacts. This circuit is traced from terminal B of the source of current through wire 17, contacts 16-36 of relay 11TR, wire 38, contacts 43-62 of relay 11H, wire 64, contacts 70 65-66 of relay 11BSB, wire 67, and winding of relay 11H and snubbing resistor 70 in parallel to terminal C of the source of current.

On completion of this circuit the winding of relay 11H is supplied with a pulse of current of 75

- sufficient magnitude to cause the relay contacts to become picked up, and on picking up of contact 62 of the relay the previously traced circuit for energizing the relay winding is interrupted.
- 5 while contact 62 engages contact 71 to establish a stick circuit for maintaining the relay winding energized as long as contact 66 of relay 11BSB remains picked up.

On picking up of contact 79 of relay 11BSB the 10 previously traced "lockout" circuit for supplying steady energy to the primary winding 74 of track transformer 10TT is interrupted, while on picking up of contact 90 of relay 11H a circuit is established to supply current of the 180 code frequency to the track transformer 10TT. This 15 circuit is traced from terminal BX of the source of current through contacts 180-94 of code transmitter 11CT, wire 93, contacts 92-90 of relay 11H, wire 89, contacts 87-79 of relay 11BSB, 20 wire 78, contacts 77-76 of relay 11FSB, wire 75, and primary winding 74 of transformer 10TT to terminal CX of the source of current.

As a result of the supply of current of 180 code frequency to the track circuit of the section 10T, 25 the signal associated with that section will display its clear aspect to indicate that there are two unoccupied blocks in advance thereof.

As a result of operation of the contacts of relay 11TR in response to current of 80 code frequency, contact 15 alternately engages contacts 110 and 112, but the frequency of the current supplied to the resonant unit 11RUA is not such as to cause this unit to pass sufficient current to energize the winding of relay 11J. Accordingly contact 103 of this relay remains released, while as contact 95 of the relay 11H is picked up, the circuit for illuminating the red lamp R of signal 11S is interrupted and the circuit for illuminating the yellow lamp Y of the signal is complete.

40 When the train advances far enough in the track stretch that the rear of the train enters the section in advance of section 12T, that is section 13T, the equipment associated with that section is conditioned to supply current of the 80 code frequency to the track circuit of section 12T.

When the train advances far enough in the track stretch that the rear of the train passes out of the track section 12T, the equipment associated with that section operates in the manner described in detail in connection with the equipment associated with section 11T to supply coded current of the 180 code frequency to the track circuit of section 11T.

On the supply of current of the 180 code frequency to the track circuit of section 11T the contacts of the track relay 11TR follow this code and the relays 11FSB, 11BSB and 11H remain energized, while resonant unit 11RUA now passes sufficient current to energize the winding of relay 11J. Accordingly contact 103 of relay 11J becomes picked up and interrupts the circuit of the yellow lamp Y of signal 11S, and completes the circuit to illuminate the green lamp G of signal 11S.

65 At this time as current of the 180 code frequency is already being supplied to the section 10T, no change is made in the code frequency.

As the train continues its movement through the track stretch and clears the section 13T in 70 advance of section 12T, the apparatus associated with that track section effects the supply of current of 180 code frequency to the track circuit of section 12T and relay 12J thereupon becomes picked up with the result that the green lamp G of signal 12S is illuminated.

The normal operation of the equipment having now been described, the operation of the equipment in the event an insulated joint separating two track sections is defective will now be considered.

Operation of equipment shown in Fig. 1 in the event of a defective insulated joint

For purposes of illustration, it will be assumed that an insulated joint separating sections 11T 10 and 12T breaks down as a result of passage of a train through the track stretch so that energy supplied to the track circuit of section 11T may feed over the defective insulated joint and energize the track relay 12TR of section 12T. 15

When the train enters section 12T, it shunts the track relay 12TR and the equipment associated with the relay operates as described in detail above to supply current of the 80 code frequency to the primary winding of track transformer 10TT. 20

As long as a portion of the train remains in section 11T, the track relay of that section is shunted, while the track relay of section 12T will continue to be shunted until the train has 25 advanced far enough in the track stretch that the rear of the train is located a substantial distance in advance of the point of connection of the relay 12TR with the rails of section 12T.

When the rear of the train vacates section 11T, 30 the track relay 11TR is no longer shunted and follows the coded current supplied to the track circuit, and the equipment associated with the track relay 11TR operates in the manner described in detail above to condition the signal 35 11S to display its yellow or caution indication, while coded current of 180 code frequency is supplied to the adjacent section in the rear.

As soon as the rear of the train passes some distance beyond the point of connection of the 40 winding of track relay 12TR with the rails of section 12T, the potential between the rails resulting from the rear section leakage energy which feeds over the faulty joint rises to a value sufficient to effect code following operation of 45 the relay 12TR.

On the first operation of the contacts of relay 12TR, that is, the first picked up period of the contacts of the relay, a circuit is established to energize the winding of relay 12FSB. This 50 circuit is traced from terminal B of the local source of current through wire 17, contacts 16-36 of relay 12TR, wire 38, contacts 39-45 of relay 12FSB, wire 46, and winding of relay 12FSB and snubbing resistor 47 in parallel to terminal C of the source of current.

On the second operation of the contact 16 of relay 11TR, that is, the first released period of the relay contacts, contact 16 engages contact 18 and establishes a circuit to energize the winding of relay 12BSA. This circuit is traced from terminal B of the source of current through wire 17, contacts 16-18 of relay 12TR, wire 20, contacts 21-27 of relay 12FSB, wire 28, contacts 29-30 of relay 12FSB, winding of relay 12BSA, 65 and snubbing resistor 34 in parallel to terminal C of the source of current.

As a result of energization of the winding of relay 12BSA, contact 55 of the relay becomes 70 picked up and establishes a circuit through which current is supplied to the winding of relay 12FSB on the next, or third operation, of the contacts of relay 12TR. On this third operation of the relay contacts, contact 16 is picked up and engages contact 36, while the circuit for energizing the winding of relay 12FSB is traced from ter- 75

5 terminal B of the source of current through wire 17, contacts 16-36 of relay 12TR, wire 38, contacts 41-55 of relay 12BSA, wire 57, contacts 58-60 of relay 12H, wire 54, and winding of 5 relay 12FSB to the terminal B of the source of current.

On energization of the winding of relay 12FSB contact 76 of the relay becomes picked up and establishes the "lockout" circuit for supplying 10 steady uncoded energy to the primary winding 74 of track transformer 11TT. This circuit is traced from terminal BX of the source of alternating current through wire 85, contacts 84-79 of relay 12BSB, wire 78, contacts 77-76 of relay 15 12FSB, and wire 75 to one terminal of the transformer primary winding, the other terminal of which is connected to terminal CX of the source of current.

As a result of the supply of steady uncoded 20 energy to the track circuit of section 11T, steady energy feeds over the defective insulated joint separating sections 11T and 12T and maintains the track relay 12TR energized with the result that contact 16 continues to engage contact 36. 25 On picking up of the contacts of relay 12FSB contact 59 establishes a stick circuit to maintain the relay winding energized after release of the contacts of relay 12BSA. This stick circuit is traced from wire 38 through contacts 42-59 of relay 12FSB, wire 51, contacts 58-60 of relay 12H, and wire 54 to one terminal of the winding of relay 12FSB, the other terminal of which is connected to terminal C of the source of current. On picking up of contact 21 of relay 12FSB, the 35 circuit for energizing the winding of relay 12BSA is interrupted and the contacts of that relay become released.

It will be seen, therefore, that on this the 40 third operation of the contacts of relay 12TR the "lockout" circuit for supplying steady energy to the adjacent track section in the rear is established, and is maintained as long as contact 16 of relay 12TR remains picked up, which contact will remain picked up as long as steady energy 45 continues to be supplied to the adjacent track section in the rear and feeds over the defective insulated joint to energize the winding of relay 12TR.

On the supply of steady energy to the track 50 circuit of the section 11T at a time when energy of the 80 code frequency has previously been supplied thereto, the contacts of the track relay 11TR are held picked up, and contact 16 does not intermittently engage contact 18 to effect the 55 supply of impulses of energy to the winding of relay 11BSB.

Accordingly after a brief time interval which is determined by the release time of relay 11BSB, the contacts of this relay become released and 60 contact 52 thereof interrupts the circuit for energizing the winding of relay 11FSB, while contact 52 also interrupts the circuit by which the snubbing resistor 40 is shunted across the winding of relay 11FSB. As a result the contacts of relay 11FSB quickly become released and contact 76 of relay 11FSB interrupts the circuit through which coded current of the 180 code frequency was supplied to the track transformer 65 10TT, and it also interrupts the circuit shunting the 80 code contact of code transmitter 11CT so that as a result of the release of the contact 79 of relay 11BSB, the previously traced circuit 70 for supplying current of the 80 code frequency to the track transformer 10TT is complete and con-

trols the supply of current to that track transformer.

It will be seen that the release of the contacts of relay 11BSB not only establishes a circuit through which current may be supplied from terminal BX of the source of signal control current to the track transformer 11TT, but it also 5 interrupts the circuit of the winding of relay 11FSB so that the contacts of relay 11FSB become released. Accordingly contact 76 of relay 10 11FSB interrupts the steady energy or "lockout" circuit for section 10T, and there is no possibility that steady energy will be supplied to the rails of section 10T at this time. Instead, as 15 pointed out above, energy of the 80 code frequency will be supplied to the track circuit of section 10T.

On release of the contacts of relay 11BSB contact 66 interrupts the circuit for energizing the winding of relay 11H, and after a time interval 20 determined by the release time of relay 11H, the contacts of this relay become released. Because of the slow releasing characteristics of relay 11H, the contacts of this relay remain picked up until after the contacts of relay 11FSB become released, and accordingly on release of contact 60 of relay 11H no circuit is established to energize the winding of relay 11FSB since contact 59 of relay 11FSB will have released before contact 60 becomes released.

On release of the contacts of relay 11H contact 95 30 interrupts the circuits of the proceed lamps G and Y of signal 11S and engages back contact 97 to complete the circuit for energizing the stop lamp R of signal 11S.

In addition, on the release of the contacts of relay 11FSB contact 39 engages contact 45 to complete the circuit for energizing the winding of relay 11FSA and the contacts of that relay become 35 picked up, but since contact 16 of the track relay 11TR remains picked up, picking up of contact 30 of relay 11FSA is without effect.

From the foregoing, it will be seen that if an 40 insulated joint separating two track sections becomes defective so that the energy supplied to the rear section feeds over the defective joint and energizes the track relay of the forward section, the "lockout" circuit will be established to supply uncoded energy to the rear section on the third 45 operation of the contacts of the track relay of the forward section, and that thereafter the contacts of the track relay of the forward section are maintained picked up by the steady energy feeding over the defective joint.

The contacts of the track relay of the forward 50 section will be held picked up even after the train has vacated the track section and coded energy is supplied to the track circuit of such forward section, since the steady energy from the rear section feeding over the defective insulated 55 joint will prevent release of the contacts of the track relay of the forward section during the "off" intervals of the coded energy supplied to the forward section. Accordingly once the "lockout" 60 circuit for supplying steady energy to the track circuit in the rear of a defective insulated joint is established, the circuit will be maintained after the track stretch becomes unoccupied.

In addition, as pointed out above, it will be 65 seen that on the supply of steady energy to the 70 track circuit of a track section as a result of the operation of the lockout circuit associated with the track relay of the adjacent track section in advance of the section to which the steady energy is supplied, the track relay of such sec- 75

tion will be steadily energized, but the lockout circuit associated with that track relay will not be established and coded energy will be supplied to the track circuit in the section in the rear of 5 that track relay.

The operation of the equipment shown in Fig. 1 in the event an insulated joint becomes defective as a result of passage of a train having been described, the operation of the equipment in the 10 event an insulated joint becomes defective when the track stretch is unoccupied will now be considered.

For purposes of illustration it will be assumed that one of the insulated joints separating the 15 track sections 11T and 12T becomes defective at a time when neither of these sections, nor the section in advance of section 12T, is occupied.

As the section in advance of section 12T is assumed to be unoccupied, coded energy of the 180 20 code frequency is supplied to the track rails of track section 12T, while the apparatus associated with the track relay 12TR operates in the manner described above to supply energy of the 180 code frequency to the rails of section 11T.

25 At this time as the track relay 12TR is responsive to energy of the 180 code, the relays 12FSB, 12BSB, 12H and 12J are energized and their contacts are picked up.

As long as the insulated joints separating the 30 sections 11T and 12T are intact, the track relays 11T and 12T will respond in the usual manner to the current of the 180 code frequency. However, when the insulated joint separating sections 11T and 12T becomes defective, assuming that it 35 breaks down to a substantially zero resistance, energy of the 180 code frequency supplied to the rails of the section 11T will feed over the defective joint and energize the winding of relay 12TR.

If at the time the joint breaks down, the impulses of coded energy supplied to section 11T are 40 out of step with those supplied to the section 12T, then the impulses of current supplied to the section 11T, and feeding over the defective joint, will fill in the spaces between the impulses of energy 45 supplied to section 12T and the track relay 12TR will be energized all or substantially all of the time, while its contacts will be maintained picked up all or a large portion of the total time.

If at the time the insulated joint breaks down 50 the impulses of coded energy supplied to the section 11T are substantially in step with those supplied to the section 12T, the winding of track relay 12TR will be supplied with current of abnormally high value, and, as a result, the contacts of the 55 track relay 12TR will occupy their picked up position for a much larger proportion of the total time than they occupy their released position. This characteristic is inherent in the single element track relay design and results from the fact 60 that abnormally high values of relay energizing current pick up the relay contacts more quickly, and introduce a corresponding delay in the release of the contacts because of the higher intensity of the magnetic flux created as a result 65 of energization of the relay winding. This flux must, of course, die down to a predetermined value before the contact carrying armature of the relay can be released under the biasing action of the 70 usual spring or of gravity.

70 In consequence of the lengthened picked up periods of the contacts of track relay 12TR, whether caused by an increase in the portion of the time during which the relay winding is energized or by an increase in the degree of energization of the relay winding, the contact 16 of

relay 12TR will not engage back contact 18, or will engage it for such short intervals that energization of the winding of relay 12BSB is reduced below the value effective to maintain the relay contacts picked up.

On release of the contacts of relay 12BSB the 5 circuits of the windings of relays 12FSB and 12H are interrupted, while the circuit connecting snubbing resistor 40 across the terminals of the winding of relay 12FSB is also interrupted so that 10 the contacts of relay 12FSB become released before the contacts of relay 12H become released.

As a result of the release of contacts of relays 12FSB and 12BSB, the circuit for supplying energy of the 180 code frequency to the rails of track 15 section 11T is interrupted, while the circuit for supplying energy of the 80 code frequency to section 11T is established. The current of 80 code frequency supplied to the rails of section 11T will feed over the defective joint and will combine 20 with the impulses of energy of 180 code frequency supplied to section 12T. The scrambled code resulting from a mixture of the impulses of the 80 and the 180 code frequency will cause the contacts of relay 12TR to remain picked up most 25 of the time, thereby energizing relay 12FSA, but within a very short time interval the relationship of the two code impulses will be such that the contacts of relay 12TR will become released and will establish the circuit for energizing the winding of 30 relay 12BSA. On subsequent picking up of the contacts of relay 12TR energy is supplied to the winding of relay 12FSB.

On picking up of the contacts of relay 12FSB the "lockout" circuit for supplying steady energy 35 to the rails of track section 11T is established, and this steady energy feeding over the defective insulated joint will maintain the contacts of track relay 12TR steadily picked up, while the relay 12TR will maintain the circuit of the winding of 40 relay 12FSB which in turn maintains the "lockout" winding of relay 12FSB which in turn maintains the "lockout" circuit intact.

At this time both of the relays 12H and 12J are 45 deenergized and the signal 12S will be conditioned to display its stop indication, while signal 11S will also be conditioned to display its stop indication.

The equipment provided by this invention and shown in Fig. 1 of the drawings will also operate in a similar manner if the insulated joint separating two track sections only partially breaks down, that is, if the joint breaks down sufficiently to permit some current to feed over the joint, but retains sufficient resistance to prevent the full value 50 of the signal control energy feeding over the joint. 55

Under such conditions if the code impulses of the sections 11T and 12T are in step, the increase in the degree of energization of the winding of relay 12TR may not be sufficient to increase the duration of the picked up periods of the relay 60 contacts, and thereby reduce the duration of the released periods of the relay contacts enough to cause the release of the contacts of relay 12BSB.

However, the coding devices 12CT and for the adjacent section in advance of section 12T are 65 operated by induction motors and the speed of these motors will vary slightly so that the in-phase relationship of the code impulses supplied by the two coding devices will not be continuous, and the code impulses, if in step at the 70 time the joint becomes defective, will soon fall out of step. As the code impulses of sections 12T and 11T approach the condition in which the "off" period of one code is filled in by the "on" period of the other code, the contacts of the 75

track relay 12TR will be picked up such a large proportion of the time that the contacts of relay 12BSB will become released and establishment of the "lockout" circuit will follow in the manner described above.

The system provided by this invention is arranged so that in the event the "lockout" circuit, when once established, is improperly interrupted, or if feeding of current over the defective joint is interrupted, the "lockout" circuit will be subsequently automatically reestablished.

For purposes of illustration it will be assumed that one of the insulated joints separating sections 11T and 12T is defective, and that the equipment associated with relay 12TR has operated to establish the "lockout" circuit to supply steady energy to the rails of section 11T, and that this steady energy feeds over the defective joint and maintains the contacts of relay 12TR constantly picked up. It will also be assumed that the track stretch is unoccupied so that energy of the 180 code frequency is supplied to the rails of section 12T, and that under these conditions the feeding of energy from section 11T to section 12T over the defective joint is temporarily interrupted.

Since it is assumed that the equipment associated with relay 12TR is conditioned to establish the "lockout" circuit, the relay 12FSB will be energized, while the other relays associated with relay 12TR will be deenergized.

When the supply of steady energy to the relay 12TR is interrupted, the contacts of the relay begin to follow the 180 code which is supplied to this section at this time. On the first "off" period in the code the contacts of relay 12TR become released, and a circuit is established to energize the winding of relay 12BSB, this circuit including contacts 21-24 of relay 12FSB. Accordingly the contacts of relay 12BSB become picked up so that on the next picked up period of the track relay contacts energy is supplied to the winding of relay 12H, while as a result of picking up of the contacts of relay 12BSB a stick circuit is established for supplying energy to the winding of relay 12FSB after picking up of the contacts of relay 12H.

On picking up of the contacts of relays 12BSB and 12H the "lockout" circuit is interrupted, while the circuit for supplying energy of the 180 code frequency to the rails of section 11T is established. On the supply of current of the 180 code frequency to the rails of section 11T the relay 11TR follows this code and the equipment associated with relay 11TR operates in the manner described above so that relays 11BSB and 11H become energized. In addition as track relays 12TR and 11TR are responding to energy of the 180 code frequency the relays 12J and 11J are energized and the green lamps G of the signals 12S and 11S are illuminated. This condition will continue as long as the track stretch is unoccupied and energy does not feed over the defective joint.

When energy again feeds over the defective joint, the contacts of relay 12TR will be held picked up an abnormally large proportion of the time and the contacts of relays 12FSB, 12BSB and 12H will become released, as explained above, thereby interrupting the supply of current of the 180 code frequency to section 11T and establishing a circuit to supply current of 80 code frequency thereto.

Subsequently relays 12FSA, 12BSA, and 12FSB will be energized successively, and on picking up

of the contacts of relay 12FSB the "lockout" circuit for supplying steady energy to the rails of section 11T will be established, and steady energy will feed over the defective insulated joint and will maintain the contacts of track relay 12TR picked up so that relay 12FSB will be maintained energized to maintain the "lockout" circuit.

The equipment will operate in a similar manner if after the "lockout" circuit is established the "lockout" circuit is temporarily interrupted.

It will be assumed that the equipment associated with track relay 12TR is conditioned to establish the "lockout" circuit to supply steady energy to section 11T and that wire 85 becomes disconnected from contact 84 of relay 12BSB to thereby interrupt the supply of steady energy to section 11T. As a result of the interruption in the supply of steady energy to the circuit of section 11T, energy no longer feeds over the defective insulated joint to relay 12TR so that relay 12TR now follows the 180 code which is supplied to the rails of section 12T.

When track relay 12TR follows code, relays 12BSB and 12H become energized, as explained above, and the "lockout" or steady energy supply circuit is interrupted, while energy of the 180 code frequency is supplied to section 11T.

The impulses of energy of 180 code frequency supplied to the rails of section 11T will feed over the defective insulated joint and energize relay 12TR. As explained above, the contacts of relay 12TR will be picked up an abnormal portion of the total time because of the increase in the energized time of relay 12TR or because of the increase in the degree of energization of the relay winding. As a result of this condition, the contacts of relay 12BSB will become released, thereby interrupting the circuits of the windings of relays 12FSB and 12H, while on the release of the contacts of relay 12FSB the circuit for energizing the winding of relay 12FSA is established and this relay becomes energized on a picked up period of the track relay contacts.

At this time as wire 85 is assumed to be disconnected from contact 84, the circuit for supplying energy of the 80 code frequency to section 11T is not complete even though contact 79 of relay 12BSB and contact 76 of relay 12FSB are released. As energy of the 80 code frequency is not supplied to section 11T, there will be no feeding of these impulses to track relay 12TR and the relay 12TR will continue to follow energy of 180 code frequency supplied to the section 12T.

On a subsequent released period of the track relay contacts relay 12BSA becomes energized, while on a subsequent picked up period of the track relay contacts relay 12FSB becomes picked up, and on picking up of the contacts of this relay a stick circuit is established to supply energy to the winding of relay 12FSB after the contacts of relay 12BSA become released.

On picking up of the contacts of relay 12FSB contact 76 establishes the "lockout" circuit and steady energy will be supplied to the rails of section 11T if wire 85 is again connected to contact 84. If wire 85 is not connected to contact 84, then on picking up of contact 76 of relay 12FSB no energy is supplied to section 11T, and hence energy does not feed over the defective joint to relay 12TR and relay 12TR continues to follow the 180 code supplied to the rails of section 12T.

If relay 12TR continues to follow code, then on the next released period of the track relay contacts after picking up of the contacts of relay

12FSB energy will be supplied to the winding of relay 12BSB. On picking up of the contacts of relay 12BSB a circuit is established to supply current to the winding of relay 12H on the next 5 picked up period of the track relay contacts, while on picking up of the contacts of relays 12BSB and 12H the circuit for supplying current of the 180 code frequency to section 11T is complete and current of this code frequency will be supplied to section 11T.

10 On the supply of energy of the 180 code frequency to the rails of section 11T the impulses of current feed over the defective joint and energize relay 12TR so that the cycle of operations outlined above will be repeated.

15 As a result of this mode of operation of the equipment, impulses of current of the 180 code frequency will be supplied to section 11T, and the signal 11S may be conditioned to periodically 20 display its yellow or green aspect. This is proper as the track sections in advance of signal 11S are unoccupied.

25 If wire 85 subsequently becomes connected to contact 84, then at the time in the cycle of operation of the relays associated with relay 12TR at which the contacts of relay 12FSB become picked up the "lockout" circuit will be established and steady energy will be supplied to the rails of section 11T, and this energy feeding over the defective joint will maintain the contacts of relay 12TR picked up and thus maintain the "lockout" 30 circuit.

35 A similar method of operation will result if the supply of steady energy to section 11T is interrupted because of breakage, disconnection or shorting of wire 75 leading to the primary winding 74 of track transformer 11TT at a time when the "lockout" circuit should be established. Under such conditions no energy is supplied to section 11T and signal 11S displays a stop indication, while relay 12TR will respond to energy of the 180 code frequency supplied to section 12T so that signal 12S will display its green aspect and the circuit for supplying energy of 180 code 45 frequency to the track transformer 11TT will be established except for the wire 75.

50 As long as the circuit of wire 75 is impaired, the condition outlined above will be continued, but as soon as the circuit of wire 75 is restored, energy supplied to section 11T will feed over the defective joint and will energize relay 12TR with the result that the equipment associated with relay 12TR will operate in the manner described 55 above to establish the "lockout" circuit to supply steady energy to section 11T. Since the circuit of wire 75 is now intact, this steady energy will reach the rails of section 11T and will feed over the defective joint and will maintain relay 12TR constantly energized so the "lockout" circuit will be maintained.

60 From the foregoing it will be seen that the system provided by this invention is arranged so that the "lockout" circuit is self-restoring in the event that after it is established it is improperly interrupted for any reason.

65 The system provided by this invention is adapted for use in track stretches which include intersections with highways as this system makes it possible to employ steady energy to discontinue operation of highway crossing signals without interfering with the operation of the signals controlling movement of traffic in the track stretch 70 75 with which the signal system is associated.

Construction of system shown in Fig. 2 of the drawings

5 Referring to Fig. 2 of the drawings, there is shown therein a stretch of railway track over which traffic normally moves in the direction indicated by the arrow, the track stretch including an intersection with a highway, the intersection being protected by crossing signals X and the railroad track stretch being equipped with signaling apparatus embodying this invention.

10 For purposes of illustration it will be assumed that the highway crossing is located in advance of signal 14S, and that the track section in advance of the signal 14S is divided into two sections identified as A14T and B14T, the insulated joints 3 separating these sections being located adjacent the highway crossing. At the cut section separating the sections A14T and B14T there is located cut section apparatus for at times supplying coded energy to the track rails of section B14T, and at other times supplying steady energy to the rails of section B14T.

15 The track stretch shown in Fig. 2 of the drawings may be assumed to be a continuation of that shown in Fig. 1 of the drawings, and impedance bonds 4 are provided to transmit propulsion current around the insulated joints which separate the various track sections, while the other parts of the system shown in Fig. 2 are the same as the 20 corresponding portions of the system shown in Fig. 1 except as hereinafter specially pointed out in detail.

25 The cut section apparatus includes a code following track relay A14TR having its winding connected to the track rails of the track section A14T through a resonant unit A14RU. The relay A14TR has associated therewith code detecting relays A14FSA and A14BSA, while contact 120 of the relay A14TR controls the circuit for energizing the relays A14FSA and A14BSA.

30 Contact 120 is constantly connected to terminal B of a local source of direct current, such as a battery, not shown, while contact 120 when picked up engages contact 122 which is connected by wire 123 to one terminal of the winding of relay A14FSA, the other terminal of which is connected to terminal C of the source of current. A snubbing resistor 125 is constantly connected across the terminals of the winding of relay A14FSA to render the relay contacts slow in releasing.

35 Contact 120 of relay A14TR, when released, engages contact 127 which is connected by wire 128 to a contact 129 which is engaged by movable contact 130 of relay A14FSA when contact 130 is picked up. Contact 130 is connected by wire 131 to one terminal of the winding of relay A14BSA, the other terminal of which is connected to terminal C of the source of current. A snubbing resistor 133 has one of its terminals connected to one terminal of the winding of relay A14BSA, while a branch of wire 128 is connected to the other terminal of the resistor. Accordingly, when contact 130 is picked up, a circuit is 40 established from wire 128 to the winding of relay A14BSA, while, in addition, the snubbing resistor 133 is connected across the winding of relay A14BSA.

45 The relay A14BSA has a contact 135 which is connected to terminal BX of the source of 100 cycle signal control current, while contact 135 when released engages a contact 136 which is connected by wire 75a to one terminal of the primary winding 74 of track transformer B14TT, 50 55 60 65 70 75

the other terminal of which is connected to terminal CX of the source of signal control current.

Contact 135 when picked up engages a contact 137 which is connected by wire 138 to contact 139, while the track relay A14TR has a contact 140 to which is connected a branch of wire 75a and which when released engages contact 139.

In addition, the relays A14FSA and A14FSB have contacts 143 and 144, respectively, which control the circuit from terminal B of the local source of direct current to one terminal of the winding 146 of interlocking relay XR, the other terminal of which is connected to terminal C of the local source of direct current.

15 The interlocking relay XR controls the crossing signals X for protecting the highway intersection. The details of construction of the interlocking relay XR are not a part of this invention and any suitable relay of standard construction may be employed.

The secondary winding of track transformer B14TT is connected to the track rails of track section B14T in the usual manner.

The equipment associated with track relay 25 B14TR, except for the additions necessary to control the circuit of the winding 148 of interlocking relay XR, is the same as that employed in the system shown in Fig. 1, and the same reference characters are employed to identify the apparatus of Fig. 2 as are employed in Fig. 1, except for a change in the designation of the relays which have been given a prefix corresponding to that of the track relay with which they are associated.

The additions necessary to control the winding 35 148 of interlocking relay XR comprises a contact 150 for relay B14FSA, a contact 151 for relay B14BSA, and a contact 152 for relay B14H. Each of these contacts has connected thereto a branch of wire 153 leading to one terminal of the winding 148 of relay XR, the other terminal of which is connected to terminal C of a source of direct current associated with track relay B14TR.

Each of the contacts 150, 151 and 152, when picked up, engages a stationary contact to which 45 is connected a wire leading from the terminal B of the local source of direct current so that the winding 148 of relay XR is energized whenever anyone of the contacts 150, 151, and 152 is picked up, and is deenergized when and only when all 50 three of these contacts are released.

Operation of equipment shown in Fig. 2 of the drawings

The construction of the equipment shown in Fig. 2 having been described, its operation will now be explained. For purposes of illustration it will be assumed that the sections B14T and A14T are unoccupied, and that the section in advance of section A14T is also unoccupied. Accordingly current of the 180 code frequency will be supplied to the rails of section A14T and the contacts of the relay A14TR will be picked up and released in accordance with this code frequency. During the picked up periods of the track relay 60 contacts, contact 120 engages contact 122 to energize the winding of relay A14FSA, while during the released periods of the track relay contacts, contact 120 engages contact 127 to supply current to the winding of relay A14BSA. It will be observed that the circuit of the winding of relay A14BSA is complete as long as contact 130 of relay A14FSA is picked up. As long as the contacts of track relay A14TR continue to follow 65 the code, therefore, the windings of relays A14FSA and A14BSA will be alternately energized, and

the contacts of these relays are slow enough in releasing to remain picked up between the impulses of current to their windings.

Accordingly contact 135 of relay A14BSA is picked up to thereby interrupt the circuit for supplying steady energy to track section B14T, while during the released periods of contact 140 of track relay A14TR, a circuit is established to supply energy to the rails of section B14T. This circuit is interrupted during the picked periods of relay 10 contact 140 so that as long as coded energy is supplied to the track relay A14TR, this relay operates to supply current of the same code frequency to the rails of section B14T.

It will be apparent that if the section in advance of section A14T were occupied and current of the 80 code frequency were supplied to the rails of section A14T, the contacts of track relay A14TR would follow this code and would supply coded energy of the same code frequency to the 15 rails of track section B14T.

As relays A14FSA and A14BSA are both energized their contacts 143 and 144 are picked up and establish the circuit for energizing the winding 20 146 of interlocking relay R.

As a result of the supply of current of the 180 code frequency to the rails of section B14T, the contacts of code following track relay B14TR are picked up and released in accordance with this code frequency. The equipment associated with track relay B14TR will operate in the manner described in detail in connection with the system shown in Fig. 1, and as long as the relay B14TR continues to follow code of the 180 code frequency, the relays B14FSB, B14BSB, B14J, and B14H will be energized and their contacts will be picked up. Accordingly the circuit for supplying current of the 180 code frequency to the section in the rear of section B14T is complete, while as the relays B14J and B14H are both energized, the contacts of these relays establish the circuit to illuminate the green lamp G of signal 30 14S.

In addition, at this time contact 152 of relay B14H is picked up and establishes connection from terminal B of the source of direct current to wire 45 153 with the result that winding 148 of interlocking relay XR is energized. As both windings of the interlocking relay are energized, this relay operates in the customary manner to maintain the crossing signals X inoperative.

Operation of equipment shown in Fig. 2 on passage of a train in normal direction of traffic

If a train traveling from left to right enters track section B14T, the wheels and axles of the 55 leading vehicle of the train will shunt the track relay B14TR and the contacts of this relay will become released. On release of the contacts of relay B14TR contact 16 no longer engages its front point of contact 36 and accordingly the contacts of relay B14FSB become released, and on the release of these contacts the circuits of the windings of relays B14BSB and B14H are interrupted and those relays become deenergized and their contacts become released.

In addition, on shunting of the relay B14TR relay B14J becomes deenergized and its contact becomes released.

On release of contact 95 of relay B14H the circuit of the green lamp G is interrupted and the 70 circuit for the red lamp R of signal 14S is established.

On release of contact 152 of relay B14H the circuit for energizing the winding 148 of interlocking relay XR is interrupted, and the armature, not 75

shown, controlled by this relay winding becomes released and initiates operation of the crossing signals X to warn users of the highway of the approach of a train.

- 5 As long as any part of the train remains in track section B14T, the track relay B14TR remains shunted and the other relays associated with this track relay remain deenergized.

When the forward portion of the train enters 10 track section A14T, it shunts the track relay A14TR, and the contact 120 of this relay no longer intermittently engages its front point of contact 122 with the result that the winding of relay A14FSA becomes deenergized and its contact 130 15 opens the circuit for energizing the winding of relay A14BSA, and, in addition, opens the circuit by means of which snubbing resistor 133 is connected across the terminals of the relay winding with the result that the contacts of relay 20 A14BSA thereafter quickly release.

As a result of release of contact 135 at this time, steady energy is supplied to the track rails of section B14T, while as a result of the release of contacts 143 and 144 of relays A14FSA and A14BSA, 25 the circuit of the winding 146 of relay XR is interrupted. However, because of the internal construction of the interlocking relay XR, on de-energization of winding 146 subsequent to de-energization of winding 148, the armature, not 30 shown, controlled by winding 146 is not permitted to move to its release position, but at this time operation of the crossing signals X is continued by the circuit controlled by the armature associated with winding 148.

35 As long as any portion of the train remains in track section B14T, the track relay of that track section remains shunted, but when the train has advanced far enough so that the rear of the train passes out of section B14T, the steady energy supplied over the circuit established by contact 135 40 of relay A14BSA to the rails of track section B14T will be fed to the winding of track relay B14TR to cause the contacts of this relay to become picked up. On picking up of contact 16 of relay B14TR 45 a circuit is established to energize the winding of relay B14FSA, this circuit being traced from terminal B of the source of current through wire 17, contacts 16—36 of relay B14TR, wire 38, contacts 39—45 of relay B14FSB, wire 46, winding of 50 relay B14FSA and snubbing resistor 47 in parallel to terminal C of the source of direct current. As a result of energization of the winding of relay B14FSA, the contacts of this relay become picked up and contact 150 establishes connection from 55 terminal B of the source of direct current to wire 153 leading to the winding 148 of interlocking relay XR.

As a result of energization of the winding 148 60 of interlocking relay XR, the armature controlled by this winding becomes picked up to interrupt further operation of the crossing signals X. On picking up of the armature controlled by the winding 148 the armature controlled by winding 146 continues to be prevented from releasing 65 with the result that operation of the crossing signals X is discontinued.

As long as steady energy continues to be supplied to the track section B14T, the contacts of relay B14TR are maintained picked up and relay B14FSA is maintained energized, while energy of the 80 code frequency is supplied to the track section in the rear of section B14T since relays B14FSB and B14BSB are both deenergized.

75 On the supply of steady energy to section B14T

and picking up of contact of relay B14TR, the relays B14J and B14H both remain released and contact 95 continues to establish the circuit for illuminating the red lamp R so that the signal 14S continues to display its stop indication.

When the train advances into the track section in advance of section A14T, the track relay for that section becomes released and the apparatus controlled by that track relay is thereby conditioned to supply current of the 80 code frequency to the rails of section A14T. As long as any portion of the train remains in section A14T, the track relay of section A14T remains released, but when the rear of the train vacates the section A14T, the energy of 80 code frequency feeds to the track relay B14TR. As a result of operation of the contacts of the track relay B14TR in response to current of the 80 code frequency, the relays A14FSA and A14BSA are energized, while contact 140 of the track 20 relay effects the supply of current of the 80 code frequency to the track rails of section B14T.

In addition, on energization of the windings of relays A14FSA and A14BSA, contacts 143 and 25 144 of those relays become picked up and complete the circuit for energizing winding 146 of interlocking relay XR. On energization of winding 146 the armature controlled by this winding becomes picked up and is removed from control by the armature associated with winding 148 of 30 the relay XR.

On the supply of current of 80 code frequency to the rails of section B14T following the period in which they have been supplied with steady energy, the contacts of the track relay B14TR 35 become released during the first "off" period in the code and effect energization of the winding of B14BSA, while on the next "on" period of the code the contacts of the track relay B14TR are picked up and energy is supplied to the 40 winding of relay B14FSB.

On picking up of the contacts of relay B14BSA contact 151 establishes a circuit from terminal B of the source of current to wire 153 so that on release of contact 150 of relay B14FSA the winding 148 of interlocking relay XR will not be de-energized.

On the next movement of the contacts of track relay B14TR to their released positions following picking up of the contacts of relay B14FSB 50 a circuit is established to energize the winding of relay B14BSB, while on picking up of the contacts of relay B14BSB a circuit is established to energize the winding of relay B14H. On picking up of the contacts of relay B14H contact 152 establishes connection from terminal B of the source of direct current to wire 153 to maintain the winding 148 of interlocking relay XR energized. The circuit for energizing the winding of relay B14BSA was interrupted on picking up of 60 the contacts of relay B14FSB, but the release time of the relay B14BSA and the pick-up time of the relays B14BSB and B14H are proportioned so that the contacts of relay B14BSA will remain 65 picked up, and contact 151 will maintain the circuit for energizing the winding 148 of interlocking relay XR until after contact 152 of relay B14H becomes picked up to establish the circuit of the winding 148 and prevent deenergization of this winding on subsequent release of the contact 151 of relay B14BSA. Accordingly 70 the winding 148 of the interlocking relay will be maintained energized throughout the cycle of operation of the relays associated with track re- 75

lay B14TR and the crossing signals X will be maintained inoperative.

On picking up of the contacts of relay B14FSB at a time when the contacts of relay B14BSB are released the steady energy supply circuit or "lockout" circuit is established to supply steady energy to the section in the rear of section B14T, while on picking up of contact 79 of relay B14BSB the "lockout" circuit is interrupted and the circuit for supplying energy of the 180 code frequency to the section in the rear of section B14T is established when contact 90 of relay B14H becomes picked up.

In addition, on picking up of the contacts of relay B14H contact 95 interrupts the circuit of the red lamp R and completes the circuit of the yellow lamp Y of the signal 14S.

The other operations of the relays B14FSB, B14BSB, and B14H are the same as described in detail in connection with Fig. 1 and will not be repeated here.

When the train has advanced far enough in the track stretch to clear the section in advance of section A14T so that current of the 180 code frequency is supplied to section A14T, the track relay A14TR repeats the supply of current of 180 code frequency to section B14T, while on the supply of current of this code frequency to track relay B14TR the resonant unit B14RUA supplies sufficient energy to relay B14J to effect picking up of the contacts of this relay to thereby extinguish the yellow lamp Y and light the green lamp G of signal 14S.

In the event an insulated joint separating section B14T and the adjacent section in the rear becomes defective so that current supplied to the rails of such section in the rear feeds over the defective joint and energizes the track relay B14TR, the equipment associated with the relay B14TR will operate in the manner described in detail in connection with the system shown in Fig. 1 of the drawings to establish the "lockout" circuit to supply steady energy to the rear section, and to maintain the contacts of the track relay B14TR picked up, while the signal S will be conditioned to display its stop indication.

When the "lockout" circuit is established, relay B14FSB is energized and its contacts are picked up, thereby interrupting the circuits of the windings of relays B14FSA and B14BSA so that the contacts 150 and 151 of those relays are released. In addition, at this time relay B14H is deenergized and its contact 152 is released. As the contacts 150, 151, and 152 are all released, no circuit is established to energize the winding 148 of interlocking relay XR, and the armature controlled by the winding 148 is released and effects operation of the crossing signals X even though a train is not approaching the highway intersection. This, however, is a safe condition.

Operation of equipment shown in Fig. 2 on passage of a train in the reverse direction of traffic

The operation of the equipment shown in Fig. 2 during passage of a train in the normal direction having been described, its operation on passage of a train in the reverse direction of traffic will now be considered. It will be assumed that the track stretch is unoccupied so that the track relay B14TR is supplied with energy of the 180 code frequency, while the signal 14S is displaying its clear indication.

When the train moving from right to left enters the section in advance of section A14T, the equip-

ment associated with that section is conditioned to interrupt the supply of current of the 180 code frequency, and to supply current of the 80 code frequency to the rails of section A14T, while track relay A14TR supplies energy of this lower code frequency to the rails of section B14T. On this change in the supply of current to section B14T to the lower code frequency the relay B14J is de-energized and the signal 14S is conditioned to display its caution indication.

At this time as track relay A14TR is following code the relays A14FSA and A14BSA are both energized, while their contacts 143 and 144 are maintained picked up and establish the circuit of the winding 146 of relay XR. In addition, at this time contact 152 of relay B14H is picked up and the winding 148 of relay XR is also energized. As both windings of the interlocking relay XR are energized, the crossing signals X are maintained inactive.

As the train proceeds to the left and enters section A14T, it shunts the track relay A14TR and the relay contacts thereafter remain in their released position. As a result, the winding of relay A14FSA is deenergized and the contacts of this relay become released. On release of contact 143 of relay A14FSA the circuit of the winding 146 of interlocking relay XR is interrupted, and the armature controlled by winding 146 becomes released, and initiates operation of the crossing signals X to warn users of the highway of the approach of a train.

On release of contact 130 of relay A14FSA the circuit of the winding of relay A14BSA is interrupted, while, in addition, the circuit by means of which snubbing resistor 133 is connected across the winding of the relay A14BSA is interrupted so that the contacts of relay A14BSA quickly become released. On release of contact 135 of relay A14BSA the steady energy supply circuit is established to supply energy to the primary winding 14 of the track transformer B14TT with the result that steady uncoded energy is supplied to the track rails of section B14T.

On the supply of steady energy to the track relay B14TR its contacts remain continuously picked up and contact 16 does not engage back point of contact 18 to supply impulses of energy to the winding of relay B14BSB. Accordingly after a brief time interval, the contacts of the relay B14BSB become released and contact 52 of the relay interrupts the circuit by means of which current is supplied to the winding of relay B14FSB, and the contacts of relay B14FSB thereupon become released. In addition, the contact 66 of relay B14BSB interrupts the energizing circuit for the winding of relay B14H so that the winding of relay B14H is deenergized and the relay contacts become released.

On release of the contacts of relay B14FSB contact 39 engages contact 45 to establish a circuit for energizing the winding of relay B14FSA with current supplied over contacts 16-36 of the track relay B14TR. Accordingly the winding of relay B14FSA will be energized and contact 150 of this relay will be picked up to establish the circuit to maintain winding 148 of interlocking relay XR energized following release of contact 152 of relay B14H. As pointed out above, contact 150 of relay B14FSA will become picked up before contact 152 becomes released, and hence winding 148 will be continuously energized.

On release of contact 95 of relay B14H the circuit for energizing the yellow lamp Y of signal 14S is interrupted and lamp R of the signal is

- illuminated to indicate that the section in advance of the signal 14S is occupied.
- At this time as the relays B14FSB and B14BSB are both deenergized, the contacts 76 and 79 of these relays are released and the circuit for supplying current of the 80 code frequency to the primary winding 74 of track transformer 13TT is complete, while the supply of current of 180 code frequency to the transformer 13TT is cut off.
- As the train continues its movement to the left and enters track section B14T, it shunts the track relay B14TR and the contacts of this relay become released and remain in their released positions. On release of contact 16 of relay B14TR the circuit for energizing the winding of relay B14FSA is interrupted, and, after a brief time interval, the contacts of this relay become released, and on release of contact 150 of relay B14FSA the circuit of the winding 148 of interlocking relay XR is interrupted, and the armature controlled by this relay winding moves toward its released position. This armature, however, is prevented from moving all of the way to its released position because of the prior release of the armature controlled by winding 146. At this time operation of the highway crossing signals X is continued by means controlled by the armature associated with winding 146 of the interlocking relay XR.
- As the train continues through the track stretch far enough so that the rear of the train is no longer present in track section A14T, the track relay A14TR will respond to coded energy supplied to the rails of section A14T by the means associated with the adjacent section in advance.
- As a result of code following operation of the contacts of relay A14TR, the relays A14FSA and A14BSA are energized and their contacts 143 and 144 become picked up and establish the circuit of the winding 146 of interlocking relay XR. As a result, the armature controlled by winding 146 becomes picked up to discontinue operation of the highway crossing signals X and to continue to prevent releasing movement of the armature controlled by winding 148.
- On picking up of contact 135 of relay A14BSA a circuit is established to supply energy to the primary winding 74 of track transformer B14TT during the released periods of contact 140 of the track relay A14TR. At this time, therefore, coded energy of the same code frequency as is supplied to track relay A14TR will be supplied to the rails of section B14T, but as long as any portion of the train remains in section B14T, the track relay B14TR will be shunted.
- When the train has advanced farther in the track stretch so that the rear of the train clears the left-hand end of section B14T, track relay B14TR responds to the coded energy supplied to the rails of this section, and on the first picked up period of the track relay contacts energy is supplied to the winding of relay B14FSA, and on energization of this winding contact 150 is picked up and establishes the circuit for energizing the winding 148 of relay XR and the armature controlled by winding 148 is then moved to its picked up position.
- The equipment associated with track relay B14TR will thereafter operate in the manner described in detail above, and its operation will not be repeated here.
- From the foregoing it will be seen that the system provided by this invention provides an improved "lockout" circuit which is non-cascading in operation, that is, on failure of an insulated joint separating two sections steady energy is supplied to the rearward one of the sections, but the supply of steady energy is not repeated beyond such rearward section.
- The non-cascading action of the system provided by this invention results from the fact that the "lockout" or steady energy circuit is not established by the first picked up period of the track relay contacts following a period during which they have been released or have been following coded energy for a substantial time. Instead the "lockout" or steady energy supply circuit is established on the second picked up period of the track relay contacts so that the "lockout" circuit is established only if after the track relay contacts have been released for a period, they follow code for a brief time interval. Similarly, if after a track relay has been following coded energy for a time interval steady energy is supplied to the track relay, the "lockout" or steady energy supply circuit will not be established.
- This method of operation insures that the "lockout" circuit will not be established if steady or non-coded energy is supplied to a track relay by means other than the lockout circuit which is controlled by the track relay, but that the "lockout" circuit will be established and will be maintained if steady energy supplied over the "lockout" circuit feeds to the track relay controlling the lockout circuit.
- Since the improved system provided by this invention is inherently non-cascading in operation, it is unnecessary to provide cut section facilities to break up cascading action, while steady energy may be employed where desired, as for example for discontinuing operation of highway crossing signals, without interfering with operation of the railway traffic governing means.
- It will be seen also that the system provided by this invention is arranged so that the lockout circuit is self-restoring, that is, if for any reason the lockout circuit should be interrupted after it has once been established the circuit will automatically restore itself.
- Although I have herein shown and described one illustrative embodiment of my invention, together with one modification thereof, it is understood that various changes and modifications may be made therein within the scope of the appended claims without departing from the spirit and scope of my invention.
- Having thus described my invention, what I claim is:
1. In a coded railway signaling system, in combination, a stretch of railway track having a pair of track rails divided by insulated joints into a plurality of successive track sections and including adjoining forward and rear track sections, means for supplying coded or uncoded energy to the rails of the forward section, a code following track relay for the forward section operated by energy received from the rails of such forward section, means operative on the release of the contacts of said track relay to establish a coded energy supply circuit to supply coded energy to the rails of said rear section, means governed by code following operation of said track relay contacts for establishing a steady energy supply circuit for supplying uncoded energy to the rails of said rear section, said means being operable to establish said steady energy supply circuit only after the track relay contacts have moved between their released and picked up positions a plurality of times, and

means also governed by code following operation of the track relay contacts for interrupting said steady energy supply circuit, said means being operable to interrupt said steady energy supply circuit only after a larger number of operations of the contacts of the code following relay than are required to establish said steady energy supply circuit.

2. In a coded railway signaling system, in combination, a stretch of railway track having a pair of track rails divided by insulated joints into a plurality of successive track sections and including adjoining forward and rear track sections, means for supplying coded or uncoded energy to the rails of the forward section, a code following track relay for the forward section operated by energy received from the rails of such forward section, means operative on the release of the contacts of said track relay to establish a coded energy supply circuit to supply coded energy to the rails of said rear section, means governed by code following operation of said track relay contacts for establishing a steady energy supply circuit for supplying uncoded energy to the rails of said rear section, said means being operable to establish said steady energy supply circuit only after the track relay contacts have moved between their released and picked up positions a plurality of times, means also governed by code following operation of the track relay contacts for interrupting said steady energy supply circuit, said means being operable to interrupt said steady energy supply circuit only after a larger number of operations of the contacts of the code following relay than are required to establish said steady energy supply circuit, and traffic controlling means governing movement of trains in said rear section, said means being responsive to energy supplied to the rails of said rear section and being selectively responsive to coded or steady energy.

3. In a coded railway signaling system, in combination, a stretch of railway track having a pair of track rails divided by insulated joints into a plurality of successive track sections, each of said sections having a code following track relay operated by energy received from the rails of such section, each of said track relays having associated therewith a steady energy supply circuit through which steady energy may be supplied to the rails of the adjacent section in the rear and a coded energy supply circuit through which coded energy may be supplied to the rails of the adjacent section in the rear, each section having means governed by the track relay for such section and controlling the associated steady energy supply circuit, each of said means being operative when the contacts of the track relay are released for a predetermined time interval to interrupt the steady energy supply circuit, each of said means being operative on initiation of operation of the contacts of the track relay to establish said steady energy supply circuit when and only when the track relay contacts have been moved between their two positions at least a predetermined number of times subsequent to the first movement of the said contacts from their released position to their picked up position, each of said means being operative to interrupt the steady energy supply circuit on a movement of the track relay contacts between their picked up and released positions subsequent to establishment of said steady energy supply circuit.

4. In a coded railway signaling system, in combination, a stretch of railway track having a pair of track rails divided by insulated joints into a plurality of successive track sections, each of said sections having a code following track relay energized by current supplied from the rails of such section, each of said track relays having contacts which occupy a released position when the relay is not energized and which occupy a picked up position when the relay is energized, each of said track relays having associated therewith a steady energy supply circuit through which steady energy may be supplied to the track rails of the adjacent section in the rear and a coded energy supply circuit through which coded energy may be supplied to the track rails of the adjacent section in the rear, each section having means governed by the track relay of such section and controlling the associated steady energy supply circuit, each of said means being operative when the track relay contacts occupy their released position for a predetermined time interval to interrupt the steady energy supply circuit, each of said means being operative on initiation of code following operation of the contacts of the track relay to establish said steady energy supply circuit only as a result of a movement of said track relay contacts between their two positions at least once subsequent to the first movement of the contacts from their released to their picked up position after being in either of their positions for a time interval, each of said means being operative to interrupt the steady energy supply circuit on a movement of the track relay contacts between their two positions subsequent to establishment of said steady energy supply circuit.

5. In a coded railway signaling system, in combination, a stretch of railway track having a pair of track rails divided by insulated joints into a forward and a rear section, means for supplying steady or coded energy to the track rails of the forward section, a code following track relay receiving energy from the rails of the forward section, said track relay having contacts which occupy a released position when the relay is not energized and which are moved to a picked up position when the relay is energized, a coded energy supply circuit through which coded energy may be supplied to the track rails of said rear section, said coded energy supply circuit being complete when the contacts of the track relay remain in their released position for a predetermined time interval, a steady energy supply circuit through which steady energy may be supplied to the track rails of said rear section, and means governed by said track relay for controlling said steady energy supply circuit, said means being operable to establish said steady energy supply circuit when and only when the contacts of the track relay move between their two positions subsequent to initial movement of the track relay contacts to their picked up position after being in their released position for a period, whereby said steady energy supply circuit will not be established on the supply of steady energy to said track relay at a time when the relay contacts have been released for a period but will be established as a result of the supply of coded energy to the track relay at such times, said means also being operative to interrupt said steady energy supply circuit on a movement of the track relay contacts subsequent to that which effects establishment of the steady energy supply circuit, whereby said steady energy supply circuit will be interrupted if the track relay con-

- tinues to respond to coded energy after establishment of said steady energy supply circuit but will be maintained if energy supplied over said steady energy supply circuit on establishment thereof feeds past an insulated joint and maintains said track relay energized.
6. In a coded railway signaling system, in combination, a stretch of railway track having a pair of track rails divided by insulated joints into a forward and a rear section, means for supplying steady or coded energy to the track rails of the forward section, a code following track relay receiving energy from the rails of said forward section, said track relay having contacts which occupy a released position when the relay is not energized and which are moved to a picked up position when the relay is energized, a coded energy supply circuit through which coded energy may be supplied to the track rails of said rear section, said coded energy supply circuit being complete when the contacts of said track relay remain in their released position for a predetermined time interval, a steady energy supply circuit through which steady energy may be supplied to the track rails of said rear section, and means governed by said track relay and controlling said steady energy supply circuit, said means being operable to establish said steady energy supply circuit on the second movement of the track relay contacts from their released to their picked up position after being in their released position for a period, whereby said steady energy supply circuit will not be established on the supply of steady energy to the track relay at a time when the relay contacts have been released for a period but will be established as a result of the supply of coded energy to the track relay at such time, said means being also operative to interrupt said steady energy supply circuit on a movement of the track relay contacts subsequent to that which effects establishment of said steady energy supply circuit.
7. In a coded railway signaling system, in combination, a stretch of railway track having a pair of track rails divided by insulated joints into a forward and a rear section, means for supplying steady or coded energy to the track rails of the forward section, a code following track relay receiving energy from the rails of said forward section, said track relay having contacts which occupy a released position when the relay is not energized and which are moved to a picked up position when the relay is energized, a coded energy supply circuit through which coded energy may be supplied to the track rails of said rear section, said coded energy supply circuit being complete when the contacts of said track relay remain in their released position for a predetermined time interval, a steady energy supply circuit through which steady energy may be supplied to the track rails of said rear section, and means governed by said track relay and controlling said steady energy supply circuit, said means being operable to establish said steady energy supply circuit on the second movement of the track relay contacts from their released to their picked up position after being in their released position for a period, whereby said steady energy supply circuit will not be established on the supply of steady energy to the track relay at a time when the relay contacts have been released for a period but will be established as a result of the supply of coded energy to the track relay at such time, said means being also operative to interrupt said steady energy supply circuit on the next

movement of the track relay contacts to their released position after establishment of said steady energy supply circuit.

8. In a coded railway signaling system, in combination, a stretch of railway track having a pair of track rails divided by insulated joints into a forward and a rear section, means for supplying steady or coded energy to the track rails of the forward section, a code following track relay receiving energy from the rails of said forward section, said track relay having contacts which occupy a released position when the relay is not energized and which are moved to a picked up position when the relay is energized, a coded energy supply circuit through which coded energy may be supplied to the track rails of said rear section, said coded energy supply circuit being complete when the contacts of said track relay remain in their released position for a predetermined time interval, a steady energy supply circuit through which steady energy may be supplied to the track rails of said rear section, and means operative on initiation of code following operation of the contacts of said track relay after the relay contacts have been released for a time interval to establish said steady energy supply circuit if and only if code following operation of said relay contacts continues after initial movement of the relay contacts to their picked up position, said means being operative to thereafter interrupt said steady energy supply circuit if and only if code following operation of the track relay continues after establishment of said steady energy supply circuit.

9. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having contacts which occupy a released position when the relay winding is not energized and which are moved to a picked up position when the relay winding is energized, a first relay energized over a front contact of said track relay, a second relay energized over a back contact of said track relay provided the contacts of the first relay are picked up, a third relay energized by current supplied over a pick-up circuit which includes a front contact of said track relay provided a contact of said second relay is picked up, a fourth relay energized by current supplied over a back contact of said track relay provided a contact of said third relay is picked up, means operative on picking up of the contacts of the third relay to establish a circuit to supply steady energy to the rails of said rear section, means operative on picking up of the contacts of the fourth relay to interrupt said steady energy supply circuit, and means operative on interruption of said steady energy supply circuit for supplying coded energy to the rails of said rear section.

10. In a coded railway signaling system, in combination with adjoining forward and rear sections of railway track which are electrically separated by insulated rail joints, means for at times supplying coded energy and at other times, supplying steady energy to the rails of said forward section, a code following track relay connected with the rails of said forward section, said track relay having contacts which occupy a released position when the relay winding is not en-

- ergized and which are moved to a picked up position when the relay winding is energized, a first relay energized over a front contact of said track relay, a second relay energized over a back contact of said track relay provided the contacts of the first relay are picked up, a third relay energized by current supplied over a pick-up circuit which includes a front contact of said track relay provided a contact of the second relay is picked up, a fourth relay energized by current supplied over a back contact of said track relay provided a contact of said third relay is picked up, means operative on picking up of the contacts of the third relay to establish a circuit to supply steady energy to the rails of said rear section, and means operative on picking up of the contacts of the fourth relay to interrupt the steady energy supply circuit and to also establish a circuit for supplying coded energy to the rails of the adjacent section in the rear.
11. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first, a second, a third, and a fourth relay, a circuit including a front contact of the track relay and a back contact of the third relay for energizing the first relay, a circuit including back contacts of the track relay and said third relay and a front contact of said first relay for energizing said second relay, a pick-up circuit for said third relay including front contacts of said track relay and said second relay, a holding circuit for energizing said third relay, said holding circuit including front contacts of the track relay and of said third relay, a circuit including a back contact of the third relay and a front contact of the third relay for energizing said fourth relay, a steady energy supply circuit including a front contact of the third relay and a back contact of the fourth relay for supplying steady energy to the rails of said rear section, and a coded energy supply circuit operative on interruption of said steady energy supply circuit to supply coded energy to the rails of said rear section.
12. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first, a second, a third, and a fourth relay, a circuit including a front contact of the track relay and a back contact of the third relay for energizing the first relay, a circuit including back contacts of the track relay and said third relay and a front contact of said first relay for energizing said second relay, a pick-up circuit for said third relay including front contacts of said track relay and said second relay, a holding circuit for energizing said third relay, said holding circuit including front contacts of the track relay and of said third relay, including front contacts of said track relay and of said third relay.
13. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first, a second, a third, and a fourth relay, a circuit including a front contact of the track relay and a back contact of the third relay for energizing the first relay, a circuit including back contacts of the track relay and said third relay and a front contact of said first relay for energizing said second relay, a pick-up circuit for said third relay including front contacts of said track relay and said second relay, a holding circuit for energizing said third relay, said holding circuit including front contacts of the track relay and of said third relay, a circuit including a back contact of the third relay and a front contact of the third relay for energizing said fourth relay, a steady energy supply circuit including a front contact of the third relay and a back contact of the fourth relay for supplying steady energy to the rails of said rear section, and a coded energy supply circuit including front contacts of said fourth relay for supplying coded energy to the rails of said rear section.
14. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first, a second, a third, and a fourth relay, a circuit including a front contact of the track relay and a back contact of the third relay for energizing the first relay, a circuit including back contacts of the track relay and said third relay and a front contact of said first relay for energizing said second relay, a pick-up circuit for said third relay including front contacts of said track relay and said second relay, a holding circuit for energizing said third relay, said holding circuit including front contacts of the track relay and of said third relay, including front contacts of said track relay and of said third relay.

a circuit including a back contact of the track relay and a front contact of the third relay for energizing said fourth relay, a snubbing resistor operative when connected across the winding of the third relay to render the relay contacts slow in releasing, a circuit including a front contact of said third relay for connecting said resistor across the winding of said third relay, another snubbing resistor operative when connected across the winding of the fourth relay to render the relay contacts slow in releasing, a circuit including a front contact of the third relay for connecting said other resistor across the terminals of the fourth relay, a steady energy supply circuit including a front contact of the third relay and a back contact of the fourth relay for supplying steady energy to the rails of said rear section, and a coded energy supply circuit operative on interruption of said steady energy supply circuit to supply coded energy to the rails of said rear section.

15. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first, a second, a third, and a fourth relay, a circuit including a front contact of the track relay and a back contact of the third relay for energizing the first relay, a circuit including back contacts of the track relay and said third relay and a front contact of said first relay for energizing said second relay, a pick-up circuit for said third relay including front contacts of said track relay and said second relay, a holding circuit for energizing said third relay, a circuit including a back contact of the track relay and a front contact of the third relay for energizing said fourth relay, a steady energy supply circuit for supplying steady energy to the rails of said rear section, said steady energy supply circuit being established on picking up of the contacts of the third relay at a time when the contacts of the fourth relay are released and being interrupted on picking up of the contacts of the fourth relay, and a coded energy supply circuit operative on interruption of the steady energy supply circuit to supply coded energy to the rails of the rear section.

16. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first, a second, a third, and a fourth relay, a circuit including a front contact of the track relay and a back contact of

the third relay for energizing the first relay, a circuit including back contacts of the track relay and said third relay and a front contact of said first relay for energizing said second relay, a pick-up circuit for said third relay including front contacts of said track relay and said second relay, a holding circuit for energizing said third relay, said holding circuit including front contacts of the track relay and of said third relay, a circuit including a back contact of the track relay and a front contact of the third relay for energizing said fourth relay, a steady energy supply circuit for supplying steady energy to the rails of said rear section, said steady energy supply circuit being established on picking up of the contacts of the third relay at a time when the contacts of the fourth relay are released and being interrupted on picking up of the contacts of the fourth relay, and means operative on release of the contacts of the third relay or on picking up of the contacts of the fourth relay for supplying coded energy to the rails of said rear section.

17. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first control relay, means controlled by contacts of said track relay for energizing said first control relay, said means being operative to energize said control relay only when the track relay contacts are following code and being operative on initiation of code following operation of said track relay contacts to effect picking up of the contacts of said first control relay only after a plurality of movements of the track relay contacts between their two positions, a second control relay, a circuit including a back contact of the track relay and a front contact of the first control relay for energizing said second control relay, a third control relay, an energizing circuit for said third control relay including a front contact of said second control relay, a holding circuit for said first control relay including front contacts of said track relay and said first control relay and a back contact of said third control relay, a steady energy supply circuit for supplying steady energy to the rails of said rear section, said steady energy supply circuit including a front contact of said first control relay and a back contact of said second control relay, and means operative on interruption of said steady energy supply circuit to supply coded energy to the rails of said rear section.

18. In a coded railway signaling system in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first control relay, means con-

- trolled by contacts of said track relay for energizing said first control relay, said means being operative to energize said control relay only when the track relay contacts are following code and being operative on initiation of code following operation of said track relay contacts to effect picking up of the contacts of said control relay only after a plurality of movements of the track relay contacts between their two positions, a second control relay, a circuit including a back contact of the track relay and a front contact of the first control relay for energizing said second control relay, a third control relay, a pick-up circuit for said third control relay including front contacts of the track relay and of the second control relay, a holding circuit for said third control relay including front contacts of said second and third control relays, a holding circuit for said first control relay including front contacts of said track relay and said first control relay and a back contact of said third control relay, a steady energy supply circuit for supplying steady energy to the rails of said rear section, said steady energy supply circuit including a front contact of the first control relay and a back contact of said second control relay, and means operative on interruption of said steady energy supply circuit to supply coded energy to the rails of said rear section.
19. In a coded railway signaling system, in combination with adjoining forward and rear sections of railway track which are electrically separated by insulated rail joints, means for at times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first control relay, means controlled by contacts of said track relay for energizing said first control relay, said means being operative to energize said control relay only when the track relay contacts are following code and being operative on initiation of code following operation of said track relay contacts to effect picking up of the contacts of said control relay only after a plurality of movements of the track relay contacts between their two positions, a second control relay, a circuit including a back contact of the track relay and a front contact of the first control relay for energizing said second control relay, a snubbing resistor operative when connected across the terminals of the winding of said second control relay to render the contacts of said relay slow in releasing, a circuit including a front contact of said first control relay for connecting said snubbing resistor across the terminals of the winding of said second control relay, a third control relay, an energizing circuit for said third control relay including a front contact of said second control relay, a holding circuit for said first control relay including front contacts of said track relay and said first control relay and a back contact of said third control relay, a steady energy supply circuit for supplying steady energy to the rails of said rear section, said steady energy supply circuit including a front contact of said first control relay and a back contact of one of the other of said control relays, and means operative on interruption of said steady energy supply circuit to supply coded energy to the rails of said rear section.
20. In a coded railway signaling system, in combination, a stretch of railway track having a pair of track rails divided by insulated joints into a plurality of successive track sections and including adjoining forward and rear sections, the forward section including an intersection with a highway and being divided by insulated joints into a first and a second portion, the first portion comprising the part of the section in advance of the intersection and the second portion comprising the part of the track section in the rear of the intersection, a first code following track relay connected to the track rails of said first portion and a second code following track relay connected to the track rails of said second portion, means for supplying coded energy to the track rails of said first portion, said first track relay being operative when and only when supplied with coded energy to supply coded energy to the rails of said second portion and being operative at other times to supply steady energy to the rails of said second portion, a crossing signal for guarding said intersection, means operative on deenergization of said second track relay to initiate operation of said crossing signal and operative on subsequent energization of said second track relay to discontinue operation of said crossing signal, means for supplying coded energy to the rails of said rear section, and a steady energy supply circuit controlled by said second track relay for supplying steady energy to

- the rails of said rear section, said steady energy supply circuit being established only after a plurality of operations of the contacts of the second track relay after initiation of code following 5 operation thereof, whereby said steady energy supply circuit is not established on the supply of steady energy to said second track relay following a period in which said track relay has been deenergized but may be established if steady 10 energy is supplied to said second track relay after a period of operation of said relay contacts, said steady energy supply circuit being interrupted on an operation of said second track relay contacts subsequent to that which effects establishment 15 thereof, whereby said steady energy supply circuit will be interrupted if the second track relay continues to follow coded energy after establishment of said steady energy supply circuit.
- 20 22. In a coded railway signaling system, in combination, a stretch of railway track having track rails divided by insulated joints into a plurality of successive block sections and including a forward and a rear section, means for at 25 times supplying coded energy and at other times supplying steady energy to the rails of said forward section, a code following track relay receiving energy from the rails of said forward section, said relay having contacts which when 30 the relay is not energized occupy a released position and which when the relay is energized occupy a picked up position, a first control relay, means controlled by contacts of said track relay for energizing said first control relay, said means being operative to energize said control relay only when the track relay contacts are following code and being operative on initiation of code following operation of said track relay contacts after they have been in either of their positions 35 for a time interval to energize said control relay only after a plurality of movements of the track relay contacts between their two positions, a second control relay, a circuit including a contact of the first control relay for energizing said second control relay, said circuit including a contact of the track relay and being complete only when the track relay contacts are in a predetermined one of their positions, a holding circuit for said first control relay including front contacts of 40 the track relay and of said first control relay and a contact which is open when the contacts of said second relay are picked up, a steady energy supply circuit for supplying steady energy to the rails of said rear section, said steady energy supply circuit including a front contact of the first control relay and a back contact of the second control relay, and means controlled by said track relay for supplying coded energy to the rails of said rear section.
- 45 23. In a coded railway signaling system, in combination, a stretch of railway track having track rails divided by insulated joints into a plurality of successive block sections and including a forward and a rear section, means for at 50 times supplying coded energy and at other times supplying steady energy to the rails of said forward section, a code following track relay receiving energy from the rails of said forward section, said relay having contacts which when the relay is not energized occupy a released position and which when the relay is energized occupy a picked up position, a first control relay, means controlled by contacts of said track relay for energizing said first control relay only when the track relay contacts are not responding to coded 55 energy, said means comprising a holding circuit which includes front contacts of the track relay and of said first control relay and a back contact of said third control relay, a steady energy supply circuit for supplying steady energy to the rails of said rear section, said steady energy supply circuit including a front contact of said first control relay and a back contact of said second control relay, and means controlled by said track relay for supplying coded energy to the rails of said rear section.
- 60 24. In a coded railway signaling system, in combination with adjoining forward and rear sections of railway track which are electrically separated by insulated rail joints, means for at 65 times supplying coded energy and at other times supplying steady energy to the rails of said forward section, a code following track relay connected with the rails of said forward section, said track relay having movable contacts which when the relay winding is not energized occupy a released position in which they engage back contacts and which when the relay winding is energized occupy a picked up position in which they engage front contacts, a first control relay, means controlled by contacts of said track relay for energizing said first control relay, said means being operative to energize said control relay only when the track relay contacts are following code and being operative on initiation of code following operation of said track relay contacts to effect picking up of the contacts of said control relay only after a plurality of movements of the track relay contacts between their two positions, a second control relay, a circuit including a back contact of the track relay and a front contact of the first control relay for energizing said second control relay, a holding circuit for energizing said third control relay, said pick-up circuit including front contacts of the track relay and of the second control relay, a holding circuit for energizing said third control relay, said holding circuit including front contacts of the third control relay and of the second control relay, means for maintaining the contacts of the first control relay picked up when the track relay contacts are not responding to coded 70 energy, said means comprising a holding circuit which includes front contacts of the track relay and of said first control relay and a back contact of said third control relay, a steady energy supply circuit for supplying steady energy to the rails of said rear section, said steady energy supply circuit including a front contact of said first control relay and a back contact of said second control relay, and means controlled by said track relay for supplying coded energy to the rails of said rear section.
- 75 25. In a coded railway signaling system, in combination with adjoining forward and rear sections of railway track which are electrically separated by insulated rail joints, means for at 75

times supplying coded energy and at other times supplying steady energy to the rails of said forward section, a code following track relay connected with the rails of said forward section, said 5 track relay having movable contacts which when the relay winding is not energized occupy a released position in which they engage back contacts and which when the relay winding is energized occupy a picked up position in which they 10 engage front contacts, a first control relay, means controlled by contacts of said track relay for energizing said first control relay, said means being operative to energize said control relay only when the track relay contacts are following 15 code and being operative on initiation of code following operation of said track relay contacts to effect picking up of the contacts of said control relay only after a plurality of movements of the track relay contacts between their 20 two positions, a second control relay, a circuit including a back contact of the track relay and a front contact of the first control relay for energizing said second control relay, a third control relay, a pick-up circuit for energizing 25 said third control relay, said pick-up circuit including front contacts of the track relay and of the second control relay, a holding circuit for energizing said third control relay, said holding circuit including front contacts of the third control 30 relay and of the second control relay, means for maintaining the contacts of the first control relay picked up when the track relay contacts are not responding to coded energy, said means comprising a holding circuit which includes 35 front contacts of the track relay and of said first control relay and a back contact of said third control relay, a steady energy supply circuit for supplying steady energy to the rails of said rear section, said steady energy supply circuit including a front contact of said first control relay and a back contact of said second control relay, a circuit including a back contact of the first control relay for supplying to the rails of the rear section energy coded at one frequency, 40 and a circuit including a front contact of one of the other control relays for supplying to the rails of the rear section energy coded at a different frequency.

26. In a coded railway signaling system, in 45 combination, a stretch of railway track having a pair of track rails divided by insulated joints into a forward and a rear section, means for supplying steady or coded energy to the track rails of the forward section, a code following track relay receiving energy from the rails of said forward section, said track relay having contacts which occupy a released position when the relay is not energized and which are moved to a picked up position when the relay is energized, a coded 50 energy supply circuit through which coded energy may be supplied to the track rails of said rear section, said coded energy supply circuit being complete when the contacts of said track relay remain in their released position for a predetermined time interval, a steady energy supply circuit through which steady energy may be supplied to the track rails of said rear section, means 55 operative on initiation of code following operation of the contacts of said track relay after the relay contacts have been released for a time interval to establish said steady energy supply circuit if and only if code following operation of said relay contacts continues after initial movement of the relay contacts to their picked up position, said means being operative to there-

75

after interrupt said steady energy supply circuit if and only if code following operation of the track relay continues after establishment of said steady energy supply circuit, and means responsive to code following operation of said track relay subsequent to establishment of said steady energy supply circuit for supplying coded energy to the rails of said rear section. 5

27. In a coded railway signaling system, in combination, a stretch of railway track having 10 track rails divided by insulated joints into a plurality of successive track sections including adjoining forward and rear sections, the forward section including an intersection with a highway and being divided by insulated joints into a first and a second portion, the first portion including the part of said forward section in advance of said highway intersection, the second portion including the part of said forward section in the rear of said highway intersection, means for supplying coded energy to the rails of said first portion of said forward section, means receiving energy from the rails of said first portion and operative when said first portion is unoccupied to supply to the rails of the second portion coded energy of the same type supplied to said first portion, said means being operative when said first portion is occupied to supply steady energy to the rails of said second portion, a code following track relay having a winding receiving energy from the rails of said second section, said track relay having contacts which occupy a released position when the relay winding is not energized and which are moved to a picked up position when the relay winding is energized, a coded energy supply circuit through which energy may be supplied to the track rails of said rear section, said coded energy supply circuit being complete when the contacts of said track relay remain in their released position for a substantial time interval, a steady energy supply circuit through which steady energy may be supplied to the track rails of said rear section, means operative on initiation of code following operation of said track relay contacts after said contacts have been 40 in their released position for a time interval to establish said steady energy supply circuit if and only if code following operation of said relay contacts continues after initial movement of the track relay contacts to their picked up position, 50 said means being operative to thereafter interrupt said steady energy supply circuit and to establish a circuit for supplying coded energy to the rails of said rear section if and only if code following operation of the track relay contacts continues after establishment of said steady energy supply circuit, a crossing signal for guarding said intersection, means operative on release of the contacts of said track relay to initiate operation of said crossing signal, means 55 operative on the first movement of the track relay contacts to their picked up position for a time interval to discontinue operation of said crossing signal, and means responsive to code following operation of said track relay contacts 60 for thereafter maintaining said crossing signal inactive.

28. In a coded railway signaling system, in combination, a stretch of railway having a pair of track rails divided by insulated joints into a 70 plurality of successive track sections including a forward and a rearward section, means for at times supplying coded energy and at other times supplying steady energy to the rails of said forward section, a code following relay having a 75

winding receiving energy from the rails of said forward section, said track relay having contacts which occupy a released position when the relay winding is not energized and which are moved to a picked up position when the relay winding is energized, a plurality of auxiliary relays associated with said track relay and including a first and a second auxiliary relay, means responsive to code following operation of the track relay contacts for effecting picking up of the contacts of said first auxiliary relay, said means being operative to effect picking up of said auxiliary relay contacts only after a plurality of movements of the track relay contacts between their two positions regardless of the initial position of the said contacts, a circuit controlled by the track relay and also by the first and second auxiliary relays for supplying energy to the first auxiliary relay to maintain the contacts of said first auxiliary relay picked up, said circuit being complete when the contacts of the track relay and of the first auxiliary relay are picked up and the contacts of the second auxiliary relay are released, means operative on continued code following operation of the track relay contacts subsequent to picking up of the contacts of the first auxiliary relay to supply energy to the winding of the second auxiliary relay to effect picking up of the contacts of said second auxiliary relay to thereby interrupt the holding circuit for the first auxiliary relay, means operative when the track relay contacts remain in their released position for a time interval to supply coded energy to the rails of said rearward section, means operative when the contacts of the first auxiliary relay are picked up and the contacts of the second auxiliary relay are released, means responsive to continued code following operation of said track relay contacts subsequent to establishment of said steady energy supply circuit to interrupt said steady energy supply circuit, means responsive to code following operation subsequent to interruption of said steady energy supply circuit for supplying coded energy to the rails of said rearward section, and means responsive to code following operation of said track relay for governing movement of traffic in said forward section.

29. In a coded railway signaling system, in combination, a stretch of railway having a pair of track rails divided by insulated joints into a plurality of successive track sections including a forward and a rearward section, means for at times supplying coded energy and at other times supplying steady energy to the rails of said forward section, a code following relay having a winding receiving energy from the rails of said forward section, said track relay having contacts which occupy a released position when the relay winding is not energized and which are moved to a picked up position when the relay winding is energized, a plurality of auxiliary relays associated with said track relay and including a first and a second auxiliary relay, means responsive to code following operation of the track relay contacts for effecting picking up of the contacts of said first auxiliary relay, said means being operative to effect picking up of said auxiliary relay contacts only after a plurality of movements of the track relay contacts between their two positions regardless of the initial position of the said contacts, a circuit controlled by the track relay and also by the first and second auxiliary relay for supplying energy to the first auxiliary relay to maintain the contacts of said first auxiliary relay picked up, said circuit being

complete when the contacts of the track relay and of the first auxiliary relay are picked up and the contacts of the second auxiliary relay are released, means operative on continued code following operation of the track relay contacts subsequent to picking up of the contacts of the first auxiliary relay to supply energy to the winding of the second auxiliary relay to effect picking up of the contacts of said second auxiliary relay to thereby interrupt the holding circuit for the first auxiliary relay, means operative when the track relay contacts remain in their released position for a time interval to supply coded energy to the rails of said rearward section, means operative when the contacts of the first auxiliary relay are picked up and the contacts of the second auxiliary relay are released to supply steady energy to the rails of said rearward section, means responsive to continued code following operation of said track relay contacts subsequent to establishment of said steady energy supply circuit to interrupt said steady energy supply circuit, means responsive to code following operation subsequent to interruption of said steady energy supply circuit for supplying coded energy to the rails of said rearward section, and means responsive to code following operation of said track relay for governing movement of traffic in said forward section.

30. In a railway signaling system of the type employing in the track circuits thereof coded current consisting of impulses of energy separated by time intervals during which the supply of energy is interrupted, in combination, a stretch of railway track having a pair of track rails divided by insulated joints into a plurality of successive track sections including adjoining forward and rearward sections, means for supplying coded or uncoded energy to the rails of the forward section, an electroresponsive device for the forward section having a winding receiving energy from the rails of said forward section, means associated with said device and operative when energy is not supplied to said device to establish a circuit to supply coded energy to the rails of said rearward section, means responsive to the initiation of the supply of coded energy to said electroresponsive device following a period during which energy has not been supplied to said device for establishing a circuit to supply uncoded energy to the rails of said rearward section, said means being operable to establish said uncoded energy supply circuit only subsequent to an interruption of the supply of energy to said device, whereby the circuit for supplying uncoded energy to the rails of the rearward section is established only if coded energy is supplied to said electroresponsive device, and means for interrupting said circuit for supplying uncoded energy to the rails of the rearward section and for establishing a circuit for supplying coded energy thereto, said means being operable to interrupt said circuit for supplying uncoded energy to the rails of the rearward section only subsequent to an interruption in the supply of energy to said electroresponsive device after the circuit for supplying uncoded energy has been established, whereby said circuit for supplying uncoded energy is interrupted only if uncoded energy supplied through said circuit does not feed to said electroresponsive device.

31. In a railway signaling system of the type employing in the track circuits thereof coded current consisting of impulses of energy sepa-

- rated by time intervals during which the supply of energy is interrupted, in combination, a stretch of railway track having a pair of track rails divided by insulated joints into a plurality of successive track sections including adjoining forward and rearward sections, means for supplying coded or uncoded energy to the rails of the forward section, an electroresponsive device for the forward section having a winding 5 receiving energy from the rails of said forward section, means associated with said device and operative when energy is not supplied to said device to establish a circuit to supply coded energy to the rails of said rearward section, means responsive to initiation of the supply of coded current to said electroresponsive device following a period during which energy has not been supplied to said device for establishing a circuit to supply uncoded energy to the rails of said rearward section, said means being operable to establish said uncoded energy supply circuit only after a plurality of impulses of energy have been supplied to said device, whereby said uncoded energy supply circuit is established only if coded 10 energy is supplied to said electroresponsive device, and means for interrupting said circuit for supplying uncoded energy to the rails of said rearward section and for establishing a circuit for supplying coded energy thereto, said means being operable to interrupt said uncoded energy supply circuit only subsequent to an interruption in the supply of energy to said electroresponsive device after the circuit for supplying uncoded energy to the rails of said rearward section has been established, whereby said circuit for supplying uncoded energy is interrupted only, if 15 20 25 30 35
- energy supplied through said circuit does not feed to said electroresponsive device.
32. In a coded railway signaling system, in combination, a stretch of railway track having a pair of track rails divided by insulated joints into a forward and a rearward section, means for supplying steady or coded energy to the rails of the forward section, a code following electroresponsive device having a winding receiving energy from the rails of the forward section, a coded energy supply circuit through which coded energy may be supplied to the rails of said rearward section, said circuit being complete when energy is not supplied to said electroresponsive device for a time interval, a steady energy supply circuit through which steady energy may be supplied to the rails of said rearward section, means responsive to the supply of coded energy to said electroresponsive device following a period during which coded energy has not been supplied to said device to establish said circuit to supply steady energy to the rails of the rearward section if and only if code following operation of said device continues subsequent to response of said device to the initial impulse of coded energy, said means being operative to thereafter interrupt said steady energy supply circuit if and only if said electroresponsive device continues to respond to coded energy subsequent to establishment of said steady energy supply circuit, and means operative on continued code following response of said electroresponsive device subsequent to establishment of said steady energy supply circuit to establish a circuit to supply coded energy to the rails of said rearward section. 30 35
